**METHOD OF AND APPARATUS FOR
SORTING COILED ARTICLES**

Mieczyslaw Budzich, Dundalk, and Edwin C. Hardesty, Perry Hall, Md., assignors to Western Electric Company, Incorporated, New York, N.Y., a corporation of New York

Filed Dec. 3, 1964, Ser. No. 415,696
14 Claims. (Cl. 209—81)

This invention relates generally to a method and a system for sorting flexible, elongated coiled articles, the sorting being based upon the results of visual examination and continuity testing of the articles. More specifically, this invention relates to a method and a system for facilitating the inspection of, and effecting the continuity testing and sorting of helically coiled spring cords, the sorting being based upon the results of the cord inspection and testing.

Certain types of electric cords, particularly spring cords currently used in the telephone industry, are formed by a number, typically four, individually insulated conductors, the conductors being encased in approximately parallel relationship by a cylindrical jacket of insulating material. The conductors generally extend from opposite ends of the jacket and have bifurcated terminals connected to the extremities thereof. In order that the cord be extensible in use, a helical, extensible coil section is provided in the cord.

Imperfect electrical connections between the bifurcated cord terminals and associated conductors, and imperfections in the cord insulation are typical defects that may be present in a spring cord which would render the cord rejectable. To determine the presence or absence of such defects, visual inspection and electrical continuity tests should be performed on every spring cord prior to assembly with other telephone components.

Known techniques for performing visual inspection of a cord, including the terminals thereof, involve tedious and time-consuming manual operations. As will be evident, the visual inspection of a spring cord is complicated and hampered by the four conductor terminals dangling from each end of the cord in a generally un-oriented manner, and by the springiness imparted to a cord by the retractile coil section. Visual inspection for observable defects, such as pinholes, in the cord insulation between adjacent coil convolutions is inhibited by the closeness of the normally retracted coils. The problem of insulation and terminal inspection is further increased with extensible cords since the cord inspector is often required to scan an effective cord length of six or more feet. Obviously, it would be advantageous to substantially eliminate the manual handling and tiring eye and head movements presently involved in inspecting this type of article.

It is conventional practice in checking spring cords for electrical continuity to test the cords by successively probing each terminal extending from one end of the cord while the cord lies in a relaxed state on a testing table with the terminals extending from the opposite cord end pressed into contact with an electrically energized conductive strip. However, since spring cords are typically in tension during telephone use, a continuity test performed upon terminals of cords that are not under forces of tension at least as great as the maximum expected in actual usage is not as revealing as a continuity test performed upon adequately tensioned conductors and terminals.

Broadly, it is an object of this invention to provide an improved method of, and a system for, determining the

2

presence or absence of prescribed defects in a finite length of a flexible, extensible, elongated article.

More specifically, it is an object of this invention to provide a method of and a system for extending a spring cord prior to the movement thereof through inspection and continuity test facilities.

Another object of this invention, in addition to the foregoing objects, is to provide a method of, and apparatus for, sorting flexible, extensible defective articles from nondefective articles of the same type.

Other objects and advantages of the present invention will be apparent from the following detailed description when considered in conjunction with the accompanying drawings, wherein:

15 FIG. 1 is a plan view of the overall apparatus constructed in accordance with this invention showing the locations of various stations;

20 FIG. 2 schematically illustrates mechanism and electrical and pneumatic circuitry utilized in accordance with the instant invention to effect cord extension, continuity testing and ejection of defective cords;

25 FIG. 3 is a side view taken along section lines 3—3 of FIG. 1 illustrating a typical pair of carriers for carrying a coiled electrical cord to a plurality of stations;

FIG. 4 is an end view taken along section lines 4—4 in FIG. 3 and illustrates one typical cord carrier;

FIG. 5 is a side view taken along section lines 5—5 in FIG. 4 of said one cord carrier;

FIG. 6 is a sectional end view taken along section lines 6—6 in FIG. 5 of said cord carrier;

FIG. 7 is a perspective of a system for driving the apparatus of this invention;

FIG. 8 is a partial side view of a cord extending station of the apparatus, the view being taken along section lines 8—8 in FIG. 1;

FIG. 9 is an end view of a cord extending station taken along section lines 9—9 in FIG. 1;

FIGS. 10—1 to 10—5, inclusive, schematically illustrate a succession of operations for extending and retaining the cord extended;

FIG. 11 is an end view of a cord reject station taken along section lines 11—11 of FIG. 1;

FIG. 12 is a plan view taken along section lines 12—12 of FIG. 11 illustrating mechanism for releasing the extended loop end of a cord at the cord reject station;

FIG. 13 is an end view of a continuity test station taken along section lines 13—13 of FIG. 1;

FIGS. 14 and 15 are partial side views of the continuity testing apparatus taken along section lines 14—14 and 15—15, respectively, in FIG. 13;

FIG. 16 is a sectional end view of the continuity testing apparatus taken along section lines 16—16 in FIG. 15;

FIG. 17 is a bottom view of the continuity testing apparatus taken along section lines 17—17 of FIG. 16 with the cord carriers removed for the purpose of clarity;

FIG. 18 is an end view of a cord ejection station taken along section lines 18—18 of FIG. 1, and

FIG. 19 is a side view of the cord ejection station taken along section lines 19—19 of FIG. 18.

According to the method and apparatus of this invention, the terminals of a spring cord are clamped adjacent one another and the resulting loop is extended and retained in the extended position during cord advancement to inspection and continuity testing stations. The extension or stretching of the cord coils permits one to readily inspect the cords for observable defects and also tensions the clamped terminals to provide an electrical connection between the terminals and test mechanism at the continuity test station. Should the cord be found defective at any station, the terminals thereof will be re-

leased so that the defective cord is ejected to locations established for rejections.

Referring now to FIGS. 3 and 18 of the drawings for a more complete understanding of the invention, a typical spring cord that is to be inspected, tested and sorted in accordance with the instant invention is indicated generally by the numeral 10. The cord 10, FIG. 18, has four individually insulated conductors 11a-11d, inclusive, the conductors having attached to their free ends respective metallic terminals 13a-13d, inclusive, and 14a-14d, inclusive. The terminals 13a-13d and 14a-14d are typically bifurcated, as indicated by the numeral 15 in FIG. 6 and are affixed by crimping terminal extensions, designated by the numerals 16, FIG. 3, into the insulation on conductors 11a-11d. Metal projections formed by the crimped extensions 16 penetrate the insulation of the conductors 11a-11d and provide electrical contact between mutually connected terminals pairs 13a, 14a, 13b, 14b, 13c, 14c; 13d, 14d and the metallic strand or strands incorporated in each conductor 11a-11d, respectively.

The conductors 11a-11d are encased in substantially parallel relationship by a plastic sheath 17. The design of the spring cord 10 may dictate that one or more conductors extending from one end of the cord 10 have a length longer than the length of the remaining conductors in that group. For example, the conductors 11c and 11d which are connected to the terminals 14c and 14d and held encased by an insulating sleeve 18, are shown to be somewhat longer than the conductors 11a and 11b which are connected to the terminals 14a and 14b, respectively.

FIG. 1 of the drawings is an overall plan view of the cord inspection, testing and sorting system constructed in accordance with the instant invention, the system being referred to by the numeral 20. The system 20 includes a horizontal base 21 and an enclosing paneling 22 extending vertically from the base 21 and suitably secured thereto. For purposes of clarity, the paneling 22 has been omitted from FIGS. 8, 9 and 13. The base 21 is supported by four or more legs, one such leg 23, being shown in FIG. 11.

With reference to FIGS. 3-6, inclusive, successive pairs of cord carriers, 24a, 24b are employed to forwardly and continuously convey individual cords 10 to the stations 1-6, inclusive, located around a vertical housing 25 mounted stationary on the base 21. The housing 25 encloses and supports the drive mechanism needed to effect the continuous advancement of the spring cords 10 as well as electrical circuitry required in the testing and rejection of defective cords at the various stations. The carrier pairs 24a, 24b, respectively, are guided for translation through station 1 and through stations 2-5, inclusive, FIG. 1, in a path parallel to the plane of the horizontal base 21, FIGS. 3 and 4, on a pair of parallel guide rails 26 and 27 affixed to the housing 25. The forward direction of carrier advancement is indicated by the arrow A in FIG. 3. The guide rails 26 and 27, FIGS. 3 and 4, are formed with grooves 28 and 29, respectively, that receive opposite ends of carrier plates 30 of the carrier pairs 24a, 24b, the plates 30 being affixed by vertically opposed pairs of angle brackets 33 to a pair of parallel roller or link chains 35. The link chains 35 mesh with and are driven at the same constant velocity by a pair of identical sprocket wheels 38, FIG. 7, mounted within and adjacent one corner of the housing 25. The wheels 38 are splined to a shaft 41 which is driven by a motor M through a conventional speed reduction box 42 in the direction indicated by arrow B in FIG. 7. The motor M, FIG. 2, is energized by a source of A.C. power S connected thereto. Identical pairs of sprocket wheels 44, 45 and 46 are mounted for rotation as shown in FIG. 7 within and adjacent the remaining three corners of the housing 25 and mesh with and support the links of the link chains 35 for forward advancement in a horizontal plane.

Referring now to FIG. 4 of the drawings, each carrier plate 30 of carriers 24a, 24b is provided with a support

plate 48 that mounts a cord terminal carrier 50 by screws 49, the plate 48 shown bent at an angle of approximately 45° with respect to the vertical axis of the carrier plate 30. The necessity for inclining the carriers 50 to the vertical axis of the carrier plate 30 will be subsequently evident. The support plates 48 advance with translation of the link chains 35 and thereby advance the carrier pairs 24a, 24b around the housing 25 with a cord 10 clamped therebetween.

If the conductors 11c and 11d, FIG. 3, are somewhat longer than the conductors 11a and 11b, it may be preferable to tension the conductors 11c and 11d so that these conductors do not dangle loosely from the carrier 24b and possibly hook onto structure located adjacent the path of advancement of the carrier 24b. The tensioning of the conductors 11a and 11b is accomplished by using a cantilevered coil spring 53, FIG. 4, which is secured at one end thereof to the support plate 48 by a bolt 54. The free end of the spring is shaped as a single downwardly extending coil element 55. A flexible coil 56 formed between the ends of the spring 53 has a flexing capability for imparting the required tension to the conductors 11c and 11d when the conductor terminals 14a-14d are clamped to the carrier 24b and the sheath 17 is hooked over the element 55.

Referring now to FIGS. 5 and 6, it can be seen that each terminal carrier 50 of each carrier pair 24a, 24b comprises three flat plates 60, 61 and 62, sandwiched together and composed of an electrical insulating material such as phenol fiberboard, the outer plates 60 and 61 securing therebetween the inner and U-shaped spacer plate 62. The spacer plate 60 is formed with four transverse terminal receiving slots 64a-64d, the edges of the slots 64a-64d being preferably reinforced with strips, not shown, of metal or wear-resistant plastic. The lateral width of the open slots 64a-64d is greater than the width of the bifurcated ends of the terminals 13a-13d and 14a-14d. The plates 60 and 61 are maintained in a spaced-apart, face-to-face relationship by the U-shaped plate 62, and all plates may be fastened together by machine screws 66, FIG. 5. The U-shaped plates 62 have a transverse width sufficient to permit pivotal movement of four metallic terminal clamping jaws 68a-68d in a plane parallel to the plane of the plate 60, the jaws 68a-68d being electrically insulated one from the other by the insulative plates 60, 61 and 62. The rearward facing edges of the jaws 68a-68d are formed with substantially U-shaped grooves 69a-69d, respectively, the grooves 69a-69d being designed for receiving and clamping the crimped extensions 16 of the terminals 13a-13d and 14a-14d against the forward edge of each slot 64a-64d, respectively, with the vertically disposed bifurcated ends 15 of the terminals 13a-13d and 14a-14d contacting opposed edges of the jaws 68a-68d.

Equally spaced, tab-like contact shoes 70a-70d, FIGS. 4 and 5, are formed on the upper ends of the jaws 68a-68d, respectively, and extend transversely from the plane of pivotal movement of the jaws 68a-68d. The contact shoes 70a-70d are designed to make electrical contact with overhead contact elements in a manner that will be subsequently disclosed in greater detail. Rectangular blocks 71a-71d, FIG. 5, are also formed on the jaws 68a-68d, respectively, and extend substantially parallel to, and in the same direction as, the contact shoes 70a-70d, respectively, from the planes of the jaws 68a-68d, respectively. The blocks 71a-71d project from the plane of the jaws 68a-68d to contact and turn the bifurcated ends 15 of the terminals 13a-13d and 14a-14d so that the bifurcated ends 15 are all oriented vertically, FIG. 6, in the carrier pairs 24a, 24b. The vertical orientation of the bifurcated ends 15 permits an inspector to readily scan the connections formed by the thusly horizontally aligned crimped sections 16.

The lower ends of the jaws 68a-68d are mounted for pivotal movement on pins 73a-73d, the outermost ends

of the pins 73a-73d being formed, FIGS. 4 and 6, with enlarged heads 74a-74d, respectively. Coil springs 75a-75d, FIG. 5, are individually supported by respective pins 73a-73d, the ends of the pins 73a-73d being affixed to the plate 60 by threaded engagement with nuts 76a-76d, respectively. The heads 74a-74d, FIGS. 5 and 6, hold the coil springs 75a-75d, respectively, against the plate 60 with spring ends 78a-78d, respectively, fixed to the plate 60 and opposite spring ends 79a-79d, respectively, fixed to the lower, pivotally mounted ends of the jaws 68a-68d, respectively. The spring ends 79a-79d, FIG. 5, are movable in arcuate slots 81a-81d, respectively, formed in the plate 60 adjacent the pivoted ends of the jaws 68a-68d and the springs 75a-75d thereby individually biasing the jaws 68a-68d counterclockwise, as viewed in FIG. 3, or clockwise, as viewed in FIG. 5, to receive and clamp all terminals pressed downwardly into the open slots 64a-64d by a cord-loading operator.

Referring now to FIG. 3, the rearwardly inclined edges of the upper end of the jaws 68a-68d and the opposite forwardly inclined edges of the slots 64a-64d, respectively, cooperate to form V-shaped openings that serve as guides when the terminals 13a-13d and 14a-14d are forced downward into the slots 64a-64d in each pair 24a, 24b, respectively. Downward pressure applied by the cord-loading operator to the terminals placed in the formed V-shaped openings will cause the extensions 16 to bear against the rearwardly inclined edges of the jaws 68a-68d and pivot the jaws 68a-68d counterclockwise. This loading operation is depicted in FIG. 5 by the crimped section 16 of the terminal 14c and the jaw 68c. In order to limit the angular displacement of the jaws 68a-68d, pins 83a-83d are mounted on the jaws 68a-68d, respectively, between the ends thereof, the pins 83a-83d extending transversely from the planes of the jaws and being received in motion-limiting arcuate slots 81a-81d, respectively, formed in the plate 61.

As mentioned hereinabove, the jaws 68a-68d may be individually pivoted against the bias afforded by the coil springs 75a-75d so as to permit the insertion of all the terminals of the conductors into the slots 64a-64d, respectively, where the crimped sections 16 are clamped between the grooved edges 69a-69d of the jaws 68a-68d, respectively, and the forward edges of the slots 64a-64d, respectively. In order to simultaneously release all terminals thusly clamped to a carrier pair 24a, 24b, the jaws 68a-68d must be simultaneously or successively pivoted to wipe off the vertically oriented bifurcated ends 15 of the terminals 13a-13d held by the opposed edges of the jaws 68a-68d against the forward edges of the slots 64a-64d. The bifurcated ends 15 of the terminals will then be released from the slots 64a-64d.

The release mechanism of each carrier pair 24a, 24b comprises a slide 87 that is preferably composed of a plastic electrical insulative material, for example, nylon, and formed with four parallel pin-driving projections that project upwardly from the upper edge of the slide 87 to bear against the pins 83a-83d, respectively. The slide 87 is mounted on the plate 61 for reciprocative movement by a pair of U-shaped brackets 88, also preferably composed of a plastic insulative material, and the bias imparted to the pins 83a-83d by the jaws 68a-68d, respectively, normally urges the slide 87 to the right as viewed in FIG. 5, so that the jaws 68a-68d substantially close the slots 64a-64d, respectively. Movement of the slide 87 from right to left, FIG. 5, is effected by pivotal movement of a bell crank 89 formed with a slide camming surface 90 that bears against one corner of the slide 87 to effect displacement thereof against the combined bias offered by spring-biased pins 83a-83d. The bell crank 89 is pivotally mounted to the plate 61 by the pin 73d and secured to the pin 73d by the nut 76d. The bell crank 89 is additionally provided with a camming roller 92 rotatively mounted to the lower end of the bell crank 89 by a pin 93. The function of the cam-

ming roller 92 is to pivot the bell crank 89 to drive the slide 87 so that the jaws 68a-68d simultaneously eject all terminals carried by a carrier pair 24a, 24b.

A flag 94 is also mounted to the plate 60 of every second carrier, that is, to every carrier 24b, by a threaded pivot pin 92 that is secured to the plate 61 by a nut 96. The flag 94 has an arcuate slot 97 that receives a pin 98 therein, the pin 98 limiting pivotal movement of the flag 94 about the pivot pin 95 to respective raised and lowered positions. The flag 94 is shown in the lowered position in FIG. 3 and is shown in the raised position by FIG. 5. The function of the raised flag 94 is to provide a signal or indication that a defective cord 10 is being carried by the carrier pair mounting the raised flag. A pin 99 projects vertically from the plane of the flag 94 and is utilized in pivoting the flag 94 from the lowered to the raised position, as will be shortly apparent.

Cord Loading Station 1

20 With reference to FIG. 1 of the drawings, the cord loading station is referred to as station 1. At this station a cord loading operator takes a cord 10 supplied to the station by a conveyor belt 106 and simultaneously grasps the bifurcated ends 15 of the four terminals 13a-13d and 25 presses the terminals and conductors attached thereto downwardly into the open slots 64a-64d in the right carrier 24a, FIG. 3, which is being advanced through station 1. The jaws 68a-68d pivot clockwise, FIG. 3, until the terminals 13a-13d are forced into grooves 69a-69d whereupon the jaws 68a-68d and the blocks 71a-71d pivot 30 counterclockwise to respectively clamp the terminals and vertically orient the bifurcated ends 15 thereof. The bifurcated ends 15 are held restrained by rearward edges of the jaws 68a-68d and the crimped sections 16 are clamped 35 between the rearward edges of the slots 64a-64d and the grooves 69a-69d of the jaws 68a-68d, respectively. The carrier pair 24a, 24b continuously advances forwardly through station 1 in the direction of arrow A, FIG. 3, driven by the continuously advancing roller or link chains 40 35. As the carrier 24b of the carrier pair approaches the position previously occupied by the carrier 24a, the operator similarly grasps the other end of the cord 10 from which the terminals 14a-14d extend and presses those terminals down into the slots 64a-64d of the carrier 24b. 45 The sheath 17 encasing the longer conductors 11c and 11d is looped under the projection 55 on the cantilevered spring 53 and the coil 56 biases the sheath 17 downwardly with sufficient force to tension the conductors 11c and 11d and thereby prevent the sheath 17 from flapping loosely against the carrier 24b. It will be noted that the flag 94 mounted on the carrier 24b is in the lowered position, the pivoting of all flags 94 to the lowered position having been effected at station 6 by mechanism that will be described subsequently.

50 55 The now-loaded carrier pair 24a, 24b advances the cords 10 around the right-hand end of the system 20, as viewed in FIG. 1, with the coils of the suspended cord 10 hanging vertically in a relaxed and retracted state. The carrier pair 24a, 24b rides off both guide rails 26 and 27 prior to 60 translation around the sprocket wheels 44. Immediately prior to, and during further carrier translation between the sprocket wheels 44 and 45, the carriers 24a and 24b are supported solely by the link chains 35.

Cord Extending Station 2

65 The carrier pair 24a, 24b carrying a spring cord 10 in a relaxed state advances to the cord extending station referred to generally as station 2, FIG. 1. As best seen in FIGS. 8 and 9, opposite ends of the carrier plates 30 are again received by the grooves 28 and 29 in guide rails 26 and 27, respectively, as shown in FIG. 8, for additional support during translation to and through station 2. Located in a horizontal plane below the rail 27 and supported by the base 21 outwardly from the path of forward advancement of the carrier pair 24a, 24b are another pair

of parallel, vertically aligned guide rails 112 and 113, respectively, and a pair of identical roller or link chains 114, also in a parallel, vertically aligned relationship and positioned for translation in the horizontal plane between the guide rails 112 and 113.

The guide rails 112 and 113 are mounted to the housing 25 at spaced intervals by support brackets 112a and 113a, respectively. The link chains 114 mesh with, and are driven in unison by, a pair of identical sprocket wheels 116, FIG. 7, and are guided for movement around the remaining three corners of the apparatus 20 by identical pairs of sprocket wheels 117, 118 and 119. The sprocket wheels 116 are driven in unison in the direction of arrow B, FIG. 7, by a link chain 121 that meshes with sprocket wheels 122 and 123 splined to shafts 41 and 124, respectively. The shaft 124 is mounted parallel to the shaft 41 on suitable bearings, not shown.

For reasons which will be subsequently apparent, every complete revolution of the sprocket wheels 118 preferably produces three complete revolutions of a cam 126, FIG. 7. The cam 126 is splined to the bearing 128 and is rotatable therewith, the bearing 128 being mounted for free rotation on a shaft 127. The shaft 127 is driven by the sprocket wheels 118 splined thereto and the bearing 128 has a spur gear 130 formed integral therewith. Thus, the cam 126 is connected to the gear 130 on the freely rotatable bearing 128. A spur gear 132 is splined to the shaft 127 so as to rotate therewith and meshes with a spur gear 133 keyed to a shaft 135, the shaft 135 being mounted parallel to the shaft 127 and driving thereby a spur gear 134 that is keyed to the shaft 135. The cam 126 mounted for free rotation on the shaft 127 is thusly driven by the shaft 127 rotating the gears 132, 133, 134 and 130 and the bearing 128. The gears 130, 132, 133 and 134 may be designed by those working in the art to drive the cam 126 the preferred three complete revolutions for every single revolution of the sprocket wheels 118.

The periphery of the cam 126 is provided with a cam lobe 126a designed to impart translation to a drive rod 138, FIG. 8, through a cam roller 139 mounted for rotation on one end of the drive rod 138 and in contact with the periphery of the cam 126. A rotor 141 is also affixed to the shaft 127 for rotation therewith and includes a lobe 142 that periodically strikes a contact pin 143 to actuate a microswitch MS1, the microswitch MS1 when actuated initiating the actuation of mechanism employed to extend the cord 10 at station 2. This mechanism will be discussed in detail subsequently.

The sprocket wheels 118, FIG. 8, mesh with the links of the identical, parallel link chains 114 and drive the chains 114 at the same velocity that the link chains 35 are driven by the sprocket wheels 38. The link chains 114, FIG. 8, mount opposite pairs of L-shaped brackets 148, the brackets 148 having rectangular plates 150 attached thereto by, for example, machine screws 152, so that each plate 150 advances vertically around the housing 25 at the same velocity as an associated pair of carriers 24a and 24b.

The plates 150, FIGS. 8 and 12, fixedly mount on the outer faces thereof, a pair of support brackets 153 and 154 that support a cord extending hook 155 for pivotal movement on a pin 156, the pin 156 being fixed at the ends thereof in the brackets 153 and 154. A coil spring 159 is supported on the pin 156 and may be attached at one end thereof to the bracket 153 and at the other end to the hook 155 adjacent the pivot point of the hook. The coil spring 159 normally biases the upper end of the hook 155 inwardly toward the outer face of the plate 150. A pin 158 is mounted on the upper end of the hook 155 and contacts the outer face of the plate 150 to incline the hook outwardly a predetermined distance from the outer face of the vertical plate 150 as the plates enter station 2. The lower end of the hook 155 mounts a roller 160 for rotation thereon, the axis of roller rotation forming substantially a right angle with respect to the lower length 75

of the hook 155 between the roller 160 and the pin 156.

The axis of symmetry of each hook 155 is positioned in substantial coalignment with the vertical axis of symmetry of its mounting plate 150, and each plate 150 is affixed to the chains 114 so that the vertical axis of symmetry of each plate 150 is substantially intermediate the vertical axes of symmetry of its associated carrier pair. Thus, each carrier pair is positioned substantially symmetrically with respect to a hook 155. The 45° inclination from the vertical provided to the plate 48 allows the cords 10 to hang in substantial vertical alignment with the rails 112 and 113. Thus, the plates 150, FIG. 8, their associated pairs of carriers 24a, 24b, and the cords 10 may be considered as forming therebetween an essentially isosceles triangle configuration, the bases of the triangle being defined by the jaws 68a-68d and the slots 64a-64d, respectively, of respective carrier pairs 24a and 24b, and the apex of the triangle being defined by a hook 155.

As the plates 150 are advanced to station 2, the plates 150 carried by the link chains 114 are received and are additionally supported for translation by the upper and lower rails 112 and 113, respectively. The hooks 155 are carried on the plates 150 in the raised position with the pins 158 abutting the outer faces of the plates 150 until the rollers 160 contact and ride along a downwardly and an inwardly curved cylindrical section 164 of a rectangular roller track 165.

The roller track 165 extends parallel to the guide rails 112 and 113 and is positioned slightly outwardly therefrom a distance sufficient to permit roller rotation between the plates 150 and the track 165. The track 165 is attached to the base 21 by angle brackets 166, and the rollers 160 are initially intercepted by, and roll against, the inwardly curved cylindrical section 164 of the track 165. The rollers 160 are driven inward by the inward bend of the section 164 and continuously pivot the hooks 155 outwardly and downwardly until the rollers 160 contact and ride upon the inner face of the rectangular roller track 165. Because the track 165 is parallel to the rails 112 and 113, while the rollers 160 ride against the track 165 the hooks 155 are maintained substantially horizontal, as best shown in FIG. 9, against the restoring bias offered by coil springs 159.

Mechanism for extending the suspended, relaxed cords 10 received by the station 2 comprises a hook-up arm 170, FIGS. 8 and 9, extending from a rotor shaft 171, the shaft 171 being rotatably driven by actuation of a conventional torque actuator 172. As viewed in FIG. 9, the torque actuator 172 may be energized and deenergized to impart respective counterclockwise and clockwise rotations to the shaft 171 through an arc of approximately 90°. The torque actuator 172 is fixedly mounted on a carriage 173, and the carriage 173 is mounted for reciprocative motion parallel to the link chains 114 on a stationary table 174, the table 174 being secured to the stationary base 21 by channel members 175. The rearward end of the torque actuator 172 mounts a bracket 176 to which the forward end of the rod 138 is connected, the rod 138 being mounted for reciprocative movement in a bearing 178 attached to the vertical side of the housing 25. Integral with the bearing 178 and extending outwardly therefrom is a support bracket 112a, best seen in FIG. 9, for supporting the rearwardmost end of the rail 112.

The rod 138 is driven forwardly, as viewed in FIG. 8, by the cam roller 139 riding against the cam lobe 126a of the cam 126. In order to bias the rod 138 rearwardly, FIG. 8, so that the cam roller 139 remains in contact with the varying contour of the cam 126, a coil spring 180 is provided, the spring 180 being fixed one end thereof to a support 181, the support 181 in turn being affixed to the carriage 173. The coil spring 180 is secured at the other end thereof to a pin 182 affixed to, and extending from, the housing 25. The uppermost end of the arm 170 is bifurcated and designed to form a pair of substantially crescent-shaped, parallel fingers 183, FIG. 9, the spacing

between the fingers 183, FIG. 8, providing a slot 185 having a width great enough to receive therein a hook 155 during the transfer of a cord loop from the fingers 183 to the hook 155.

Referring now to FIG. 2, as mentioned hereinabove, the rotor lobe 142 periodically contacts and depresses thereby the contact pin 143 to initiate the closing of the microswitch MS1. The microswitch MS1 is electrically connected to the source S by leads L1 and to a conventional four-way solenoid spool valve SV1. The solenoid valve SV1 receives air under pressure from a tube 191 connected to a supply of pressurized air 192 and is also provided with a tube EX1 that exhausts the valve SV1 to atmosphere. The solenoid valve SV1 is connected to tubes 193 and 194, respectively, the tubes 193 and 194 being connected to speed control valves 195 and 196, respectively. The speed control valves 195 and 196 are connected by tubes 197 and 198, respectively, to the torque actuator 172. The function of the speed control valves is to control the velocity of air supplied to the torque actuator 172, thereby controlling the velocity of rotation of the shaft 171.

With the START and STOP switches closed, the initiation of the microswitch MS1 by the rotor lobe 142 depressing the contact pin 143 allows the source S to energize and drive the four-way solenoid valve SV1 in one direction so that air under pressure received by the valve SV1 from the supply 192 is diverted through the valve into the tube 193, for example, through the speed control valve 195 to the tube 197, and hence to the torque actuator 172. The pressurized air supplied to the torque actuator 172 from the tube 197 rotates the shaft 171 and the arm 170 counterclockwise as shown schematically by FIGS. 10-1 to 10-3, inclusive, from the upward position downwardly through an arc of approximately 90°.

When the lobe 142 rides off and releases the contact pin 143, the microswitch MS1 again initiates the solenoid valve SV1 to move in a reverse direction, so that pressurized air from the supply 192 is diverted by the valve SV1 into the tube 194, through the speed control valve 196 and into the tube 198 causing the arm 170 to swing upwardly and to the raised position as shown in FIG. 10-5. Assuming that the arm 170 is in the raised position, FIGS. 8 and 10-1, after having completed the transfer of a cord loop to a hook 155, the periphery of the cam 126 is designed to change abruptly at this time to permit the hitherto extended coil spring 180 to retract and pull the torque actuator 172 and the arm 170, through the carriage 173, rearwardly, as viewed in FIG. 8, until the arm 170 reaches the rearwardmost position shown by the dotted lines. Rotation will not be imparted to the arm 170 during this rearward movement of the actuator 172, and the velocity of the return stroke of the torque actuator 172 and the arm 170 is preferably at least one and one-third times greater than the forward velocity of the plates 150. The next successive plate 150 and the carrier pair 24a, 24b associated therewith will have advanced forwardly of the rearwardmost position of the arm 170 and will continue to advance forwardly.

As soon as the arm 170 reaches the end of the return stroke thereof, the design of the cam 126 is such that the roller 139 and the rod 138 drive the torque actuator 172 forwardly, as viewed in FIG. 8, with a predetermined acceleration sufficient for the arm 170 to overtake the rearwardmost carrier plate 24b of the carrier pair and move into vertical alignment with the hook 155 positioned intermediate the carrier pairs. The fingers 183 on the arm 170 will then be behind a successive suspended relaxed cord loop and positioned to intercept the lowermost end of the cord loop. The configuration of the cam 126 now changes slightly so that the same constant velocity of the carrier pair 24a, 24b and associated plate 150 is imparted to the rod 138 and thusly to the arm 170, whereupon the arm 170 and the successive carrier pair 24a, 24b translates forwardly at substantially the same velocity. The rotor

141 will now have rotated to the position where the lobe 142 depresses the contact pin 143 of the microswitch MS1, FIG. 2, thereby reenergizing the solenoid valve SV1 and causing downward rotation of the arm 170 through an angle of approximately 90°.

As best seen in FIG. 10-2, the downward rotation of the arm 170 causes the crescent-shaped fingers 143 to intercept the vertically suspended loop end of the cord 10 and upon further counterclockwise rotation of the arm 170, FIG. 10-3, the cord 10 is stretched over the hook 155 with the hook 155 positioned between the loop end of the cord 10 and the shaft 171 and within the slot 185. The extension of the cord 10 pulls the bifurcated ends of the terminals 13a-14d into firm contact against the jaws 68a-68d and uniformly tensions all the cord terminals. During the period when the cord is looped over the hook 155, both hook 155 and arm 170 continue to translate forwardly together at substantially the same velocity.

After the cord 10 is extended, FIG. 8, the translating roller 160 pivots inwardly under the influence of the inwardly curved track section 164 and the hook 155 is thereby pivoted outwardly and downwardly to intercept the loop of the cord presented to the hook 155 by the fingers 183. The inward bend provided the track section 164 causes further pivotal movement of the hook 155 in a direction of the arrow, as shown in FIG. 10-4, as the arm 170 and the hook 155 continue to translate together. Finally, the inward bend of the track 164 causes sufficient angular displacement of the hook 155 so that the hook 155 pulls the extended cord 10 outwards and from contact with the fingers 183. The rotor lobe 142 thereupon rides off and releases the contact pin 143, FIG. 2, thereby reactuating the microswitch MS1.

The reactuation of the microswitch MS1, FIG. 2, effects the reenergization of the solenoid valve SV1 so that the pressurized air from the supply 192 is diverted into the tube 194, through the speed control valve 196 and through the tube 198 and into the torque actuator 172 to impart clockwise rotation to the shaft 171, FIG. 10-5. An exhaust to atmosphere is also provided by the tube EX1 for air that is forced through the return tube 197, the speed control valve 195 and the tube 193. During the upward return movement of the arm 170, the track 164 may provide further downward pivotal movement to the hook 155 until the convolutions of the coils of the cord 10 are extended the desired amount. The transfer of the extended cord to the hook 155 is thereby effected and the upwardly raised arm 170 thereafter proceeds to return to the rearwardmost position for a subsequent cord extending cycle.

Every complete revolution of the shaft 127, FIG. 7, presents three carrier pairs 24a, 24b, respectively, and three cords 10 for hookup to three corresponding plates 150. Therefore, the cam 126 which drives the hookup arm 170 will reciprocate the arm 170 forwardly and through a complete hookup cycle three times for every complete revolution of the shaft 127. Consequently, the aforementioned three-to-one ratio provided between the cam 126 and the sprocket wheels 118 is required in order that the arm 170 complete the hookup of three successive cords for each complete revolution of the shaft 127 and the sprocket wheels 118.

As seen in FIGS. 8 and 9, the substantially V-shaped cord configuration provided by the extension of the lowermost end of the cord loop defines a plane which is inclined at an acute angle, considerably less than a right angle, with respect to the vertical plane of the freely suspended, relaxed cords received by station 2. The advantage in providing a V-shaped configuration to the spring cords 10 and the slight inclination to the plane of the advancing extended cords from the vertical will be realized subsequently.

Cord inspection and rejection station 3

The extended spring cords 10 advancing forwardly of station 2 are received by station 3, FIG. 1. At station

3, FIG. 11, a rectangular mirror 201 is located between the carriers 24a, 24b and the housing 25 and is inclined at approximately 45° to the vertical side of the housing 25 against which the mirror 201 is suitably affixed. The mirror 201 is long enough to permit an inspector at station 3 to scan the horizontally aligned and adjacent bifurcated ends 15 and the crimped sections 16 of the advancing set of terminals 13a-13d and 14a-14d for defects.

The substantially V-shaped configuration of the spring cord 10 and the prior vertical orientation of the bifurcated ends 15 by the blocks 71a-71d permits the inspector to readily and easily examine the adjacent and aligned bifurcated ends 15 of the cord 10 by glancing into the mirror 201 while simultaneously scanning the horizontally aligned and adjacent crimped sections 16 to see if there is apparent connective integrity between the crimped sections 16 and the insulation of conductors 11a-11d. This visual examination may be accomplished with minimum horizontal head and eye movement, as will be apparent. The doubling of the cord 10 around the hook 155 further permits the inspector to scan the insulative covering of the cord 10 with minimum vertical head and eye movement. Defects in the insulation of the coil convolutions, such as pinholes, will be increased in size by the cord extension and thus may be readily detected by the inspector. If necessary, the mirror 201 may extend downwardly and behind the entire cord 10 to permit an examination of the complete periphery of the coil convolutions. If the inspector observes a defect in the cord which might render the cord rejectable, the hitherto lowered flag 94, FIG. 5, is manually raised as illustrated by the dotted lines in FIG. 11 while the carrier pairs 24a, 24b continue to advance past the inspector.

At station 3, a flat plate 203, FIGS. 11 and 12, is secured to the base 21 and two pairs of vertical supports, referred to by numerals 204 and 205, respectively, are vertically attached to the plate 203. Support pairs 204 and 205 mount therebetween horizontal, parallel rods 206 and 207, respectively, the rods 206 and 207 having coils 208 and 209 thereon that bear against sleeves 211 and 212, respectively. The sleeves 211 and 212 are slideable on the rods 206 and 207, respectively, and are biased by the coils 208 and 209, respectively, inwardly toward the track 165. The plate 215 is positioned between the innermost supports 204 and 205 and the sleeves 211 and 212, respectively, and is guided for reciprocative movement upon the rods 206 and 207 in directions perpendicular to the longitudinal axis of the track 165 and to the forward direction of translation of the cords 10, as indicated by the arrow A in FIG. 12.

The plate 215 has affixed thereto a moveable track section 220 and thereby mounts the innermost face of the track section 220 for advancement into, and retraction from, alignment with the innermost face of the track 165. Retraction of the track section 220 from the normal position where the innermost face of the section 220 is flush with the innermost face of the track 165 is effected by an initial actuation of an air cylinder 222 mounted stationary on the plate 203. The air cylinder 222 encases a piston rod 223 for reciprocative movement and acts through the piston rod 223 to axially retract and advance the piston rod 223 and the plate 215 which is affixed to the rod 223 by bolts 224. Located adjacent the air cylinder 222 and affixed to the plate 203 is a microswitch MS2 having a contact button 228 extending inwardly therefrom toward the plate 215, and the button 228 is positioned to be depressed by contact with the plate 215 retracting from the track 165. Depression of the button 228 effects through circuitry to be disclosed in detail subsequently, the return actuation of the air cylinder 222.

Prior to initiation of the microswitch MS2 by the plate 215, the outward displacement of the section 220 presents a gap in the track section 165 and a roller 160 advancing past this gap will be free to pivot outwardly under the bias

of the coil spring 159, whereupon the associated hook 155 pivots and releases the extended loop of the cord 10. The resilience of the cord 10 causes the cord to retract and hang in a relaxed state suspended at the free ends thereof by the carrier pair 24a, 24b.

Upon subsequent initiation of the microswitch MS2 by the plate 215 depressing the contact button 228, the air cylinder 222 will again be actuated to drive the rod 223 inwardly thereby returning the track section 220 to the normal position where the section 220 is again flush with the track 165, FIG. 12, thusly providing an uninterrupted track surface for the roller 160 of the next succeeding plate 150. The aforescribed release of the looped end of the cord 10 by the outward movement of the track section 220 is initiated by the inspector raising the flag 94, as will be shortly apparent.

As best seen in FIG. 11, a terminal release mechanism, designated TRM and delineated by the dotted lines, is mounted to the housing 25 at station 3. The terminal release mechanism TRM includes an overhead bracket 229 fixedly mounted to the top of the housing 25 and a conventional photoelectric detector set, referred to generally by the numeral 230, is attached to the underside of the bracket 229.

The detector set 230 includes a light source 231 for emitting a beam of light onto a photosensitive cell 232 that is positioned to receive the energy of the light beam. The beam of light will be interrupted only when the flag 94 is in the raised position.

An air cylinder 242 encasing a reciprocatively driveable piston rod 243 is secured to the housing 25 by a bracket 252, and one end of the piston rod 243 is connected by an L-shaped support 253 to an arm 254. The arm 254 is pivotally connected at one end thereof to a bracket 256 fixed to the housing 25. The other end of the arm 254 has attached thereto a terminal release plate 260, the terminal release plate 260 extending beneath the camming rollers 92 of the carrier pairs 24a, 24b that translate past station 3. The terminal release plate 260 is normally beneath and out of contact with camming rollers 92 that advance thereover.

A chute 265 extends from the housing 25 outwardly a distance sufficient to receive defective cords that are released from a carrier pair 24a, 24b. The chute 265 extends parallel to the rails 112 and 113 and is located between laterally adjacent rail supports 112a and 113a, respectively, so that the cords do not fall upon a rail support when the cords are released from carrier pairs 24a, 24b. The chute 265 communicates with a bin, not shown, for receiving cords having observed defects therein.

Referring now to FIG. 2, when switch START is closed, and with switch STOP closed, the A.C. power source S is applied to the secondary winding of a step-down voltage transformer XF1 which is connected by leads L2 to the light source 231, and by leads L3 to a conventional time delay relay TR1. The relay TR1 is connected by leads L4 in circuit with an amplifier AMP1 and the amplifier AMP1 is connected by leads L5 to the photosensitive cell 232 of the photodetector set 230. The relay TR1 is also electrically connected by leads L6 to a conventional four-way solenoid spool valve SV2, the valve SV2 being connected by tubes 236 and 237 to opposite ends of the air cylinder 222. Initiation of the relay TR1 closes contacts associated therewith, not shown, and holds these contacts closed for a relatively short period of time, for example, one-half of a second. This time interval is long enough for the valve SV2 to be electrically energized and driven in one direction to direct pressurized air received from the supply 192 through the tube 236 and into the air cylinder 222 so that the piston rod 223 is driven through a prescribed displacement from right to left, as viewed in FIGS. 2 and 11. To reduce the build-up in back pressure against the piston rod 223 as the piston is driven from right to left, an exhaust to atmosphere is provided through the tube 237, through the solenoid valve SV2 and to an exhaust tube EX2 communicating with the

valve SV2 at one end thereof and with atmospheric pressure at the other end thereof.

After the relay TR1 has effected timed energization of the solenoid valve SV2 by the relay TR1 closing internal contacts, the relay TR1 deenergizes and these contacts are then reopened, whereupon the solenoid valve SV2 is driven by, for instance, an internal spring, not shown, in an opposite direction to divert pressurized air into the air cylinder 222. The piston rod 223 is thereupon driven outwardly to restore the track section 220 to a position flush with the track 165. Back pressure that may be developed in the air cylinder 222 by the return movement of the piston rod 223 is alleviated by exhaust to atmosphere by way of the tube 236, the solenoid valve SV2 and the tube EX2.

The microswitch MS2 is connected to the source S by leads L7, and as discussed hereinabove, the microswitch MS2 is actuated by depression of the contact button 228. The actuation of the microswitch MS2 effects energization of a conventional three-way solenoid spool valve SV3 to which the microswitch MS2 is connected by leads L8. Selective energization of the valve SV3 effects the axial displacement of the piston rod 243 in the air cylinder 242. The solenoid valve SV3 is connected by a tube 244 to the supply of pressurized air 192 and the air issuing from the supply valve SV3 is received by either the tube 246 or the tube 247 communicating with opposite respective ends of the air cylinder 242. Pressurized air received by the tube 246 resulting from initial energization and movement of the valve SV3 will drive in the piston rod 243, the back pressure being alleviated through the tube 247, through the valve SV3 and from an exhaust tube EX3 communicating with the valve SV3 at one end thereof and with atmospheric pressure at the other end thereof. Pressurized air diverted into the tube 247 by the reenergization of the valve SV3 will drive the piston rod 243 outward from the air cylinder 242. Any back pressure developed by outward piston rod movement will be relieved by way of flow through the tube 246, through the valve SV3 and through the exhaust tube EX3 to ambient pressure.

Upon energization of the solenoid valve SV3 resulting from the initiation of the microswitch MS2, the resulting outward movement of the piston rod 243 will drive the release plate 260 upwardly, FIG. 11, and the release plate 260 will thereupon simultaneously engage and force the cam rollers 92 from both carriers 24a and 24b translating thereover at that time upwardly a distance sufficient to impart linear displacement to the slide 86, from left to right as viewed in FIG. 3. The slide 86 moving against the pins 83 will pivot the jaws 68a-68d to open the slots 64a-64d, respectively, and simultaneously eject the bifurcated ends 15 of the cord terminals 13a-13d and 14a-14d from the carrier pair 24a, 24b. The released cord 10 will then fall by gravity into the chute 265 and hence into the reject bin, not shown.

The time delay relay TR1, FIG. 2, will now have completed a timing cycle and will thereupon open internal contacts, not shown, to effectuate the deenergization of the solenoid 222 so that the plate 215 is moved inwardly and out of contact with the contact button 228 to a position flush with the track 165. The release of the contact button 228 effects the reenergization of the solenoid valve SV3, whereupon the piston rod 243 is pulled back into the air cylinder 242 thereby lowering the release plate 260, FIG. 11, beneath the rollers 92 of the next succeeding carrier pair 24a, 24b.

The operation of the visual inspection station 3 may be summarized as follows. If the operator visually detects a defect in a cord 10 as the cord advances past station 3, the flag 94 on the carrier 24b will be manually raised, and as the carrier 24b thereafter translates past the terminal release mechanism TRM, the beam of light between the light source 231 of the photodetector set 230 will be interrupted and an electrical current pulse will be

received and amplified by the amplifier AMP1 and supplied to initiate the operation of the time delay relay TR1. When initiated, the relay TR1 closes and holds closed hitherto open contacts thereby completing the circuit between the source S and the solenoid valve SV2. The energized solenoid valve SV2 will be driven to provide a confined path for air under pressure from the supply 192 to the tube 236. Pressurized air egressing from the tube 246 enters the innermost end of the air cylinder 222 and drives the piston rod 223 and the track section 220 attached thereto outwardly to the left, FIGS. 2 and 11.

The gap produced in the track 165 by outward displacement of the track section 220 causes the forwardly advancing roller 160 carried by advancing plate 150 to roll off the edge of the track 165 adjacent the rearward-most edge of the track section 220. The tension applied to the hook 150 connected to the roller 160 by the extended cord 10 and the tension applied to the hook 155 by the coil spring 159 effect swift pivotal movement of the hook 155 in a clockwise direction, as viewed in FIG. 11, thereby releasing the hitherto extended loop end of the cord 10. The released cord springs upwardly and assumes a relaxed state held vertically suspended by the cord terminals 13a-13d and 14a-14d to the forwardly translating carrier pair 24a, 24b, respectively. The released roller 160 advances forwardly in a horizontal plane above the plane of the track 165 to station 1.

After the hook 155 releases the cord loop, the plate 215 continues to move outwardly from the track 165 until the button 228 is contacted and depressed by the plate 215 to actuate the microswitch MS2. The time delay relay TR1 continues to hold the internal contacts thereof closed so that the solenoid valve SV2 remains energized to retain the plate 215 in the outermost position where the plate 215 depresses the button 228. Thus, the microswitch MS2 is not released until completion of the timing cycle of the relay TR1. The actuation of the microswitch MS2 effects the initial energization of the air solenoid valve SV3, FIG. 2. The solenoid valve SV3 will be driven to provide a confined path for pressurized air from the air supply 192 through the tube 244 to the tube 247. The pressurized air issuing from the tube 247 drives the piston rod 243 outwardly from the air cylinder 242.

The outward movement of the piston rod 243, FIG. 11, causes upward pivoting of the release plate 260 against both cam rollers 92 of the carrier pair 24a, 24b holding the terminals of the relaxed defective cord 10. Upward movement of the release plate 260 against the rollers 92 simultaneously releases the terminals 13a-13d and 14a-14d of the cord 10 from the carrier pair 24a, 24b. When the terminals 13a-13d and 14a-14d are released, the cord drops by gravity into the reject chute 265.

Substantially concurrent with the release of the terminals 13a-14d from the carrier pair 24a, 24b, the timing cycle of the relay TR1 will be completed and hitherto closed internal relay contacts will be opened to effect the deenergization of the solenoid valve SV2. The deenergized solenoid valve SV2 is thereupon driven to provide a path for pressurized air from the supply 192 through the tube 237 so that the piston rod 223 is driven inwardly toward the track 165 until the track section 220 is returned to the position where the innermost face of the section 220 provides a surface flush with the innermost face of the track 165 against which succeeding rollers 160 may roll. As the plate 215 moves from left to right, FIG. 2, the hitherto depressed contact button 228 is released thereby reinitiating the microswitch MS2. The reinitiation of the microswitch MS2 effects the reenergization of the solenoid valve SV3 so that the solenoid SV3 is driven to provide a path for pressurized air from the air supply 192 through the tube 246 and into the air cylinder 242. As a result, the piston rod 243 will be pulled in and the terminal release plate 260, FIG. 11, pulled down to the position where the plate 260 is again

beneath and out of contact with the advancing rollers 92 of the next succeeding carrier pair 24a, 24b. Obviously, if the flag 94 is not raised by the inspector at station 3, the cord 10 will not be rejected at this station and will continue to advance to station 4.

Modified embodiment of station 3

A modification of station 3, FIG. 11, involves the removal of the plate 203 and all mechanism supported thereon and utilized to effect the hereinabove described release of the loop end of a cord. In this embodiment the track 165 is continuous throughout the length of station 3. The chute for receiving rejected cords is positioned outwardly of the track 165 and in substantially transverse alignment with the terminal release mechanism TRM. The leads L6 are connected to the solenoid SV3 so that the solenoid SV3 is selectively energized and deenergized by operation of the tuning relay TRI to effect outward and inward movement of the piston rod 243. The release of the cord 10 is initiated by the inspector raising the flag 94. As should be evident, the interruption of the light beam of the detector set 230 by a raised flag 94 would ultimately effect the actuation of the solenoid SV3 so that the terminal release plate 269 is driven upwardly and downwardly, FIG. 11, by timed movement of the piston rod 243 to release the terminals 13a-13d, 14a-14d from a carrier pair 24a, 24b.

The hook 155 in this embodiment does not pivot during advancement past station 3 and serves instead as a member about which the released, retracting cord flings itself into the aforementioned chute positioned outwardly of the track 165. In accordance with this modification, the energy which is applied to stretch the cord is thereafter utilized to fling rejectable cords into the rejection chute.

Continuity test station 4

At station 4 the advancing extended cords 10 are tested for electrical continuity between the terminal pairs 13a, 14a-13d, 14d, inclusive. The drive for station 4 is shown partially by FIG. 7 as comprising sprocket wheels 46 driven by the link chains 35 and splined to rotate a drive shaft 301, the shaft 301 having a sheave 302 splined thereto for rotation therewith. A drive belt 303 is positively driven by the sheave 302, the belt 303 in turn positively driving a sheave 304. The sheave 304 is splined to a shaft 305 and drives a bevel gear 306 that is also splined to the shaft 305. The bevel gear 306 meshes with a bevel gear 307 keyed to a shaft 308, the shaft 308 having a sheave 309 fixedly mounted thereon. The sheave 309 drives a sheave 310 through a drive belt 311.

As best seen in FIG. 13, the shaft 308 is mounted for rotation in a bearing 312, the bearing 312 being mounted in one leg of a substantially L-shaped panel 313. The panel 313 is bolted or otherwise secured at an end 313a to the top of the housing 25. A channel 314 having a C-shaped cross section is secured to the panel 313 and comprises two parallel side plates 314a and 314b and an end plate 314c integral with the side plates 314a and 314b. The side plate 314a is secured to the underside of the panel 313 by bolts 316, and is formed with an inwardly extending shaft-mounting plate 317. The side plate 314b is also formed with a pair of outwardly extending, parallel, shaft-supporting plates 318.

The shaft-supporting plate 317 mounts the downwardly inclined end of the shaft 308 in a bearing 321, the bearing 321 being mounted for rotation in the plate 317. In order to prevent axial movement of the shaft 308, collars 322 and 323 are provided adjacent the bearings 312 and 321, respectively, the collars 322 and 323 being fixed to the shaft 308 for rotation therewith.

The sheave 310 is splined to a shaft 319 which is substantially parallel to the shaft 308, and is mounted for rotation by coaligned bearings 332 in the support plates 318. Axial movement of the shaft 319 is prevented by

collars 335 positioned adjacent the bearings 332. The shaft 319 drives a cam 336 keyed to the shaft 308, and the periphery of the cam 336, FIG. 15, contacts a cam follower roller 337 mounted for rotation on a bracket 340. The bracket 340 is mounted by bolts 342 to a vertically moveable support plate 344. The periphery of the cam 336 is formed with a cam lobe 336a which imparts vertical upward movement to the cam roller 337 and to the plate 344.

10 The plate 344 mounts two pairs of vertical supports 345 and 346 adjacent respective ends of the plate 344. Supports 345 and 346 mount therebetween a pair of parallel rods 348, the ends of the rods 348 being fixed to respective pairs of supports 345 and 346 by connector pins 349. The rods 348 are slidable in respective pairs of spaced-apart bearings 352 and 353, FIGS. 15 and 16, the pairs of bearings 352 and 353 being fixedly attached to a table 354. The table 354 is preferably composed of a plastic electrical-insulating material, such as nylon or Teflon. A coil spring 350 is supported on each rod 348 between bearings 352 and 353 that are located proximate opposite ends of each rod 348. The forwardmost end of the coil spring 350 abuts the bearing 352 and the rearwardmost end of the spring 350 abuts a collar 351, the collar 351 being fixed to the rod 348. The tension applied to the coil springs 350 may be varied by adjustment of the collar 351 on the rod 348, as will be evident.

15 The support plate 344 is guided in vertical reciprocative movement, as indicated by the arrows C-C in FIG. 15, by an essentially identical pair of vertically slidable rods 355 having respective reduced diameter ends 355a secured to opposite corners of the plate 344 by machine screws 356. The rods 355 are mounted for reciprocative movement in respective stationary, vertical, cylindrical casings 357, the casings 357 being affixed by brackets 358 to the underside of the stationary side plate 314b. The respective opposite ends 355b of the rods 355 are threaded to receive machine screws 360 having coil springs 361 thereon. One end of each coil spring 361 abuts a head 363 of a screw 360 and the other end of each spring 361 abuts a disc 364 stationary on the downwardmost end of the casing 357. The tension applied by each coil spring 361 biases the rods 355 vertically downward and the coil springs 361 compress when the plate 344 and the rods 355 are driven upwardly by the cam rollers 337 riding in contact with the cam lobe 336a on the periphery of the cam 336.

20 Referring to FIGS. 13 and 14, the periphery of the cam 326 contacts a cam follower roller 370 which is mounted for rotation on one end of a rod 371, the rod 371 being mounted for reciprocative movement in directions indicated by the arrows D-D in FIG. 14 on a pair of spaced-apart bearings 372. The bearings 372 are mounted stationary to the underside of the side plate 314a. At the opposite end of the rod 371 another roller 373 is mounted for rotation thereon, the roller 373 riding against a leg 375a of a channel 375 having an L-shaped cross section, the channel 375 being fastened by bolts 376 to the upper surface of the table 354. The length of the vertically-disposed leg 375a of the channel 375 is long enough so that the roller 373 remains in contact with the channel leg 375a during maximum vertical displacement of the table 354.

25 The L-shaped panel 313, FIG. 15, mounts a solenoid S380 adjacent the outermost end thereof, the solenoid S380 comprising a solenoid plunger 381 which is pivotally connected by a pin 382 to the upper end of a link 383. The lower end of the link 383 is pivotally connected by a pin 384 to a link mounting 385. The link mounting 385 is integral with, and extends upwardly from, the forwardmost or free end of a flag raising plate 386.

30 The rearwardmost end of the plate 386 is pivotally mounted to a downwardly extending support 390 and

hence to the panel 313 by a pivot pin 391. The plate 386 is biased clockwise, as viewed in FIG. 15, by a coil spring 387 supported by a pin 344. The pin 344 is slidably mounted in the panel 313 for vertical reciprocal movement in the direction of arrows C—C. The lower end of the coil spring 387 abuts the uppermost surface of the plate 386 and the other upper end of the spring 393 abuts the underside of the panel 313. The coil spring 387 normally biases the plate 386 to a substantially horizontal position so that the plate 386 is normally in a horizontal position beneath and out of contact with the pins 99 that project from the flags 94 of the carriers 24b that advance in a horizontal plane through station 4. The plate 386 remains normally horizontally suspended by the plunger 381 and the link 383.

When the solenoid S380 is energized, the solenoid plunger 381 will pull in thereby pulling up the link 383 to pivot the free end of the flag-raising plate 386 about the pin 391 in a counterclockwise direction as viewed in FIG. 15. The plate 386 will then provide an inclined surface that intercepts the path of a forwardly advancing pin 99 and carried by a flag 94 shown by phantom lines in FIG. 15. The hitherto lowered flag 94 is pivoted through contact of the pin 99 with the inclined plate 386 and advancement of the flag supporting carrier 24b past plate 386 will effect the pivoting of the flag 94 to the raised position. As will be apparent, if the solenoid S380 is not energized, the plate 386 will remain horizontal, and the pin 99 will pass over the plate 386 without raising the flag 94 mounting that pin 99.

As best shown by FIGS. 16 and 17, the table 354 is covered by a flat plate 390, also preferably composed of a plastic insulating material. The carrier pair 24a, 24b is omitted from FIG. 17 for the purpose of clarity. A flat, substantially L-shaped metal strip 393, and flat, parallel metallic strips 394a-394d are positioned between mutually opposed surfaces of the table 354 and the plate 390 and a suitable insulating adhesive 391 bonds the table 354 and the plate 390 together with the individually insulated, parallel conductive strips therebetween. The terminal of the L-shaped conductive strip 393 is connected at one end thereof to a lead 396 and the terminals of conductive strips 394a-394d are electrically connected to leads 398a-398d, respectively.

The upper surface of the insulating plate 390, FIG. 16, mounts a bracket 401, preferably composed of a plastic insulating material, by means of bolts 402. The bracket 401 extends transversely outward a short distance from the outermost edge 354a of the table 354 and from the outermost edge 390a of the plate 390. The bracket 401 has a lateral dimension greater than the overall lateral distances between the forwardmost and rearwardmost edges of any carrier pair 24a, 24b, respectively. The lateral length of the bracket 401 is substantially coextensive with the lateral length of the edge 390a. A rectangular strip 405, preferably composed of plastic insulating material, extends parallel to the outermost face of the bracket 401 and is coextensive with the lateral length of the bracket 401. The outermost face of the bracket 401, FIG. 17, is formed to provide two laterally aligned groups of substantially semicircular grooves 407, each group of grooves having four equally spaced grooves in substantially transverse alignment with four laterally aligned, substantially semicircular grooves 408 formed in the adjacent face of the strip 405. Each pair of grooves 407 and 408 in respective transverse alignment receives a cylindrical plunger casing 409, FIGS. 16 and 17, and the strip 405 fixedly secures the two groups of cylindrical plunger casings 409 in lateral alignment to the outermost face of the bracket 401 by machine screws 411 or the like. The casings 409 are composed of metal or other electrical conducting material, and each casing 409 encases a vertically movable, spring-biased contact pin designated generally by the numeral 413.

Attached to the downwardmost projecting ends of the two groups of contact pins 413, FIGS. 16 and 17, by, for example, soldering or welding, are two groups of cantilevered leaf-like contacts K1-K4 and K5-K8, respectively. The two respective groups of contacts K1-K4 and K5-K8 are bent inwardly proximate the free ends thereof, as best shown in FIG. 16, so that the free end of each contact will contact a crimped section 16, FIG. 15, of a terminal 13a-14d. The primary function of the contacts K1-K8 is to force the bifurcated ends 15 of the terminals 13a-14d against the jaws 68a-68d and thereby insure positive electrical contact between the jaws and the terminals. A conductive strip 415, FIGS. 16 and 17, may be connected at one end thereof by, for example, soldering or welding, to each metallic plunger casing 409 and each strip 415 is held encased in the insulated bracket 401. The opposite end of each strip 415 may be connected by soldering or welding to transversely adjacent metal cylindrical plunger casings 416.

The casings 416 may be inserted with an interference fit into vertical bores 417 extending through the table 354 and through the plate 390 adjacent the outermost edges 354a and 390a, respectively. The uppermost ends of the casings 416 abut the underside of the bracket 401, as seen in FIG. 16. Each plunger casing 416, FIG. 17, encases a vertically movable, downwardly projecting, spring-biased pin contact, and the contacts of each respective group are designated as K1A-K4A, inclusive and K5A-K8A, inclusive. Thus, the strips 416 electrically connect insulated, transversely adjacent contact pairs K1, K1A; K2, K2A; K3, K3A; K4, K4A of one group of contacts and also electrically connect insulated, transversely adjacent contact pairs K5, K5A; K6, K6A; K7, K7A; and K8, K8A of the second group of contacts.

Assuming a carrier pair 24a, 24b is advancing past station 4 and beneath the panel 313, FIGS. 15 and 16, the lateral spacing between the contact pairs K1A-K4A is substantially equal to the lateral spacing between the contact shoes 70a, 70b, 70c and 70d mounted on the carrier 24a so that electrical contact may be made between the projecting contacts K1A-K4A, inclusive, and the jaws 68a-68d, respectively, of the carrier 24a. Similarly, the lateral spacing between the downwardly projecting contacts K5A, K6A, K7A and K8A is substantially equal to the lateral spacing between contact shoes 70a, 70b, 70c and 70d, respectively, and the jaws 68a-68d, respectively, mounted on the carrier 24b, so that electrical contact may also be made between the contacts K5A-K8A, inclusive and the jaws 68a-68d respectively.

Electrical current supplied from the source S, FIG. 2, is applied to the lead 396, FIG. 17, and divides equally to each contact pair K5, K5A-K8, K8A. As discussed hereinabove, the current flows through the jaws 68a-68d, FIG. 5, of the carrier 24b; through the conductors 11a-11d to the terminals 13a-13d, respectively; and thus to the jaws 68a-68d, respectively, mounted by the carrier 24a. The tension applied to the cord terminals by extending the cord coils at station 2 so that defects in the cord may be readily examined also serves to pull the bifurcated ends 15 of the contact terminals 13a-13d, into firm electrical contact against the opposed edges of the jaws 68a-68d.

If there is electrical continuity, FIG. 15, between each terminal pair 13a, 14a-13d, 14d, inclusive, the current supplied by the lead 396 to the contacts K5, K5A-K8, K8A, and thus to the terminals 14a-14d, will pass through the extended conductors 11a-11d, respectively, of the cord 10. The currents in the conductors 11a-11d will be received by the terminals 13a-13d, respectively, and by the contact pairs K1, K1A-K4, K4A, which are now in parallel with the terminals 13a-13d, respectively, to receive current from the terminals 13a-13d by virtue of their contact with these terminals. The current received by either one of the respective contact pairs K1, K1A,

K4, K4A, FIG. 17, will be received by the conductive strips 394a-394d, respectively, and hence by the leads 398a-398d, respectively.

Since the carrier pairs 24a, 24b continuously advance past station 4, FIG. 15, a complete cycle of movement of the table 354 and the bracket 401 involves vertical and horizontal displacement such that the overhead contacts K1-K8A, move downwardly and into electrical contact with the terminals of the cord 10 carried by each carrier pair 24a, 24b, remain in contact with the terminals long enough to effect the continuity test between terminal pairs 13a, 14a-13d, 14d, and thereafter move upward and out of contact with the terminal pairs. The required vertical and horizontal displacement is provided by the continuous rotation of the cams 326 and 336 which are synchronized with the movement of the link chains 35, FIG. 7, through the sprocket wheel 46, sheaves 302 and 304, bevel gears 306 and 307 and sheaves 309 and 310, FIG. 13, and associated shafts.

Assume that the table 354 has advanced forwardly, or from right to left as viewed in FIG. 14, by the cam roller 370 riding off the cam lobe 326a of the cam 326 and releasing the coil spring 350, FIG. 15, for expansion. During forward advancement of the table 354, the cam roller 337, FIG. 15, will have ridden off the cam lobe 336a of the cam 336 and the plate 354 will be in the furthermost downward position. As soon as the hereinafter disclosed continuity test is completed, the cam 336 rotates to the position where the cam roller 337 rides upon the cam lobe 336a, and further rotation of the cam 336 causes the cam roller 337 to be driven upward, driving the table 354 and the bracket 401 upward. As the table 354 and the bracket 401 progress upwardly, the cam lobe 326a, FIG. 14, of the cam 326 will ride against the cam roller 370 so that the table 354 and the bracket 401 are also simultaneously shifted rearwardly. During initial upward displacement of the table 354 and the bracket 401, contact will be broken between the contacts K1-K8A and the terminals 13a-14d. After contact is broken and as the table 354 and the bracket 401 progress to the upper limit of vertical movement as determined by the cam lobe 336a, the further rotation of the cam 326 will then cause horizontal rearward shifting of the table 354 and the bracket 401 to the rearwardmost limit as determined by the cam lobe 326a. Thus, the resultant of vertical upward displacement of the table 354 by rotation of the cam 336 and horizontal displacement of the plate 354 by rotation of the cam 326 will shift the table 354 and the bracket 401 upwardly and then rearwardly to an elevated rearward position awaiting the arrival of the next advancing carrier pair 24a, 24b.

During the interval when the next succeeding forwardmost carrier 24a advances to a position substantially under the rearwardmost group of contacts K5-K8 and K5A-K8A, the cam 336 will have rotated to a position where the cam roller 337 begins to ride off the cam lobe 336a. The cam 326 will also have rotated to a position where the cam roller 370 begins to ride off the cam lobe 326a. Further rotation of the cams 326 and 336 will effect the lowering and simultaneous forward advancement of the table 354 and the bracket 401. The cam 326 may be designed so that the table 354 is accelerated forwardly, driven by the expansion of the coil spring 350, while moving downward under the control of the cam 336 until the contacts K1A-K4A and the contacts K5A-K8A are in vertical alignment with the shoes 70a-70d of each carrier 24a and 24b, respectively, and the contacts K1-K4 and the contacts K5-K8 are in vertical alignment with the crimped sections 16 of the terminals 13a-13d and 14a-14d, respectively. The cam 326 is also designed such that the table 354 and the bracket 401 translate forwardly at substantially the same velocity as the carrier pair 24a, 24b. Electrical contact will be made between the contacts K1-K8A and the terminals 13a-14d as the table 354 and the bracket 401 move further downward

under the control of the rotating cam 336 while translating forwardly under the control of the rotating cam 326 at the same velocity as the velocity of the carrier pair 24a, 24b.

As soon as contact is made between the contacts K1-K8A and the terminals 13a-14d, a subsequently disclosed continuity test is effected. After the continuity test is performed, the cam lobe 336a of the cam 336 rides against the cam roller 337 to drive the table 354 and the bracket 401 vertically upward so that electrical contact between the contacts and terminals is broken. As soon as this contact is broken, the cam 326, FIG. 16, will have rotated to again shift the table 354 rearwardly and upwardly to await the arrival of the next succeeding carrier pair 24a, 24b. The aforescribed cycle will be repeated as each carrier pair advances into station 4.

After contact is made between the forwardly moving contacts K1-K8A and the advancing terminals 13a-14d of a cord 10, current will be supplied to the lead 396, FIG. 17, and to the strip 393 and hence to the rearward contacts K5-K8 and K5A-K8A, respectively. As discussed hereinabove, if there is electrical continuity between all terminal pairs 13a, 14a-13d, 14d, the contact pairs K1, K1A-K4, K4A, receive and supply current to the leads 398a-398d, respectively. The contacts K1-K4 and K5-K8, which force the bifurcated ends 15 of the terminals 13a-14d against the jaws 68a-68d also make electrical contact with the conductors 11a-11d through the crimped sections 16, and increase the probability that adequate electrical contact has been made between the terminal pairs 13a, 14a-13d, 14d.

If there is no electrical continuity between one or more terminal pairs 13a, 14a-13d, 14d, the solenoid S380 will be energized through circuitry, that will be subsequently disclosed; and the energized solenoid S380 will pull in the solenoid plunger 381 thereby pivoting and raising the free end of the flag raising plate 386. The resulting inclination of the plate 386, as previously discussed will effect the raising of the flag 94 carried by the carrier 24b as the carrier 24b proceeds to advance past the plate 386. As soon as the flag 94 is raised, the solenoid S380 may be deenergized, allowing the hitherto compressed coil spring 387 to expand and restore the plate 386 to the horizontal position. The carrier pairs 24a, 24b carrying the defective cord 10 will continue to advance to a reject station 5, as indicated by the phantom lines in FIG. 14, with the flag 94 raised on the carrier 24b.

Referring now to FIG. 13, the shaft 305 that drives the mechanism of station 4 has two cams 425 and 426 splined thereto and rotatable therewith. The cams 425 and 426 are formed with cam lobes 425a and 426a, respectively, that project outwardly from the periphery of the cams 425 and 426. The cam lobes 425a and 426a are designed to depress and release after predetermined intervals, the contact buttons 430 and 431, respectively, that project outwardly from limit switches LS1 and LS2, respectively. The limit switches LS1 and LS2 are mounted stationary on the housing 25 by a panel member 435 affixed to the top of the housing 25.

The cam 425 is positioned on the shaft 305 and the cam lobe 425a is designed such that the cam lobe 425a depresses the contact button 430 of the limit switch LS1 at the same instant that the cam lobe 426a of the cam 426 depresses the contact button 431, whereupon the limit switches LS1 and LS2 are closed at substantially the same instant. The cam lobe 425a is also designed to release the contact button 430 before the cam lobe 426a releases the contact button 431 so that the limit switch LS1 is opened a predetermined period of time before the limit switch LS2 is opened. The rotation of the cams 425 and 426 on the shaft 305 is, of course, synchronized with the movement of the table 354 and the bracket 401. The synchronization is such that the limit switches LS1 and LS2 are closed by rotation of the cams 425 and 426, respectively, after the aforescribed electrical contact is

made between the forwardly and downwardly moving contacts K1-K8A and the forwardly advancing terminals 13a-14d; and the limit switches LS1 and LS2 are opened just prior to the breaking of contact between the contacts K1-K8A and the terminals 13a-14d. As soon as contact is made between the downwardly moving and advancing contacts K1-K8A and the advancing terminals 13a-14d, the hereinafter disclosed continuity test is performed.

Continuity test circuit

The circuitry for effecting the continuity testing of the cords 10 at station 4 in accordance with the instant invention is shown in FIG. 2. Referring now to that figure, with the START and STOP switches closed, the A.C. source S supplies power to the step-down transformer XF2 and thus to the continuity test circuit, designated CTC. The circuit CTC receives current from the lead 396 connected to the secondary coil of the transformer XF2, and includes the parallel contact pairs K1, K1A; K2, K2A; K3, K3A; K4, K4A; K5, K5A; K6, K6A; K7, K7A; and K8, K8A. During the period when contact is made between the forwardly advancing contacts K1-K8A and the forwardly advancing terminals 13a-14d at station 4, the four conductors 11a-11d of each cord 10 are respectively connected in series with contact pairs K1, K1A and contact pairs K5, K5A; with contact pairs K2, K2A and contact pairs K6, K6A; with contact pairs K3, K3A and contact pairs K7, K7A; and with contact pairs K4, K4A and contact pairs K8, K8A, as will be apparent. Contact pairs K1, K1A; K5, K5A are in series with a control relay CR15; contact pairs K2, K2A; K6, K6A are in series with a control relay CR26; contact pairs K3, K3A; K7, K7A are in series with a control relay CR37; and contact pairs K4, K4A; K8, K8A are in series with a control relay CR48. Control relays CR15, CR26, CR37 and CR48, when energized, are designed to open normally closed contacts K15, K26, K37 and K48, respectively. A control relay CR10 is connected in series with the limit switch LS1 and is designed to close normally open contacts K10 when energized. The normally open contacts K10 are in circuit with a conventional timing or time delay relay TR2 having normally open contacts K30 in circuit with the solenoid S380.

As mentioned hereinabove, the limit switches LS1 and LS2 are simultaneously closed by the rotation of the cam lobes 425a and 426a of the cams 425 and 426, respectively, FIG. 13, after contact is effected between the forwardly advancing contacts K1-K8A and the forwardly advancing terminals 13a-14d of a cord 10, FIG. 15. When the limit switch LS1 closes, FIG. 2, the control relay CR10 is energized by the source S to close the normally open contacts K10.

If there is electrical continuity between all terminal pairs 13a, 14a; 13b, 14b; 13c, 14c; 13d, 14d, respectively, the relays CR15, CR26, CR37 and CR48 will be simultaneously energized by current flow through at least one contact of each contact pair K1, K1A-K8, K8A. The energization of all relays CR15, CR26, CR37 and CR48 opens all the hitherto closed contacts K15, K26, K37 and K48, respectively. The limit switches LS1 and LS2 now close; but because the contacts K15, K26, K37 and K48 are open, no energizing current will be received by the time delay relay TR2. The contacts K30 will remain open, the solenoid S380 will not be energized and the carrier 24b will translate past station 4 with the flag 94 remaining in the lowered position.

If there is no electrical continuity between any one terminal pair 13a, 14a-13d, 14d, the control relay CR15, CR26, CR37 or CR48 connected to the noncontinuous or open circuit terminal pair will not be energized; and consequently, the normally closed contact K15, K26, K37 or K48, respectively, will remain closed. After the limit switches LS1 and LS2 simultaneously close, the circuit from the source S to the time delay relay TR2 will be completed, and the relay TR2 will be energized to close

the contacts K30. Once the relay TR2 is initially energized, the relay TR2 will hold in for a predetermined period; and thus, the limit switch LS1 may be opened by the cam lobe 425a riding off and releasing the contact button 430 of the limit switch LS1, FIG. 13, without affecting the running of the time cycle of the relay TR2. The opening of the limit switch LS1 causes the deenergization of the control relay CR10 and the consequent re-opening of the contacts K10.

10 The rotation of the cam 425 is synchronized with the rotation of the cams 326 and 336, FIGS. 14 and 15, such that as soon as the limit switch LS1 is reopened, the table 354 and the bracket 401, FIG. 15, may be driven upward by the cam lobe 336a of the cam 336 so that electrical contact between the terminals under test and the contacts K1-K8A is broken. Since the limit switch LS1 has been reopened, no arcing will occur between these contacts. When electrical contact between the terminals 13a-14d of the contacts K1-K8A is broken, the control relays CR15, CR26, CR37 and CR48 will be simultaneously deenergized and the contacts K15, K26, K37 and K48, respectively, will pull in and close.

15 The energization of the time delay relay TR2, FIG. 2, closes the contacts K30; and since the limit switch LS2 is closed, the solenoid S380 will be energized by the source S and remain energized during the time interval prescribed by the time delay of the time delay relay TR2. The energized solenoid S380 will pull in the solenoid plunger 381 and hold the plunger 381 pulled-in so that 20 the flag 94 mounted on the carrier 24b will be raised as the carrier 24b advances past station 4 while the table 354 and the bracket 401 are returning to the rearward, elevated position. After a predetermined period of time sufficient to effect the raising of the flag 94 through 25 energization of the solenoid S380, the timing cycle of the relay TR2 will be completed so that the relay TR2 is deenergized to reopen the contacts K30, thereby deenergizing the solenoid S380. Shortly thereafter, the limit switch LS2 is opened by the cam lobe 326a riding off 30 the contact button 431 of that switch LS2. The afore-described continuity testing cycle will be repeated as successive carrier pairs 24a, 24b advance past station 4.

Modification of station 4

35 It may be desired to further insure that adequate contact has been made between the contacts carried by the table 396 and the bracket 401 and the terminals 13a-14d by providing in addition to the first and second contact groups, that is, contact group K1, K1A-K4, K4A, and contact group K5, K5A-K8, K8A, respectively, herein-after referred to as the "forward contact groups," a third and fourth group of contacts. The third and fourth groups of contacts, herein-after referred to as the "rearward contact groups," are constructed essentially identical to the forward contact groups. The third and fourth groups of contacts are mounted and electrically connected in the same arrangement and manner as corresponding contact pairs of the forward contact groups on a rearwardly extending section of the table 396 and bracket 401. The substantially transversely aligned rearward contact pairs corresponding to the contact pairs K1, K1A; K5, K5A; K4, K4A; K8, K8A of the forward contact groups are also connected in series by the four terminal pairs 13a, 14a-13d, 14d to control relays CR15, CR26, CR37 and CR48, respectively, when electrical contact is made between the forwardly advancing respective contact groups and an advancing set of terminals of a cord 10 carried by each respective carrier pair 24a, 24b. The control relays CR15, CR26, CR37 and CR48 will be energized when electrical continuity exists between the terminal pairs 13a, 14a-13d, 14d and either the rearward contact groups or the forward contact groups that are horizontally and vertically driven to make respective electrical contacts with each set of advancing terminals carried by each carrier pair 24a, 24b.

The limit switches LS1 and LS2 will close by rotation of the cams 425 and 426 when the forwardly advancing contact groups make electrical contact with the terminals 13a-14d carried by a carrier pair 23a, 24b, and the previously described continuity test cycle would thereupon begin. Thus in accordance with this modification of station 4, since the control relays CR15, CR26, CR37 and CR48 will be energized in the event continuity is found between the cord terminals of a cord by either of two successively performed tests, the possibility that improper contact between the terminals 13a-14d and the contacts carried by the table 396 and the bracket 401 might result in an erroneous rejection of a nondefective cord at station 5 is substantially reduced.

Cord rejection station 5

After the cords 10 advance forwardly from the continuity test at station 4, the cords are received at station 5. At station 5 the track 165 terminates, FIG. 1, so that those rollers 160 which are still in contact with the track 165 roll off the end of the track 165 and release the hooks 155 for upward pivotal movement. The hooks 155 thereupon release the loop ends of the cords 10 and the cords 10 further advance through station 5 in a substantially relaxed state hanging suspended by the terminals 13a-13d and 14a-14d from carrier pairs 24a, 24b, respectively.

If a cord 10 fails the continuity test at station 4, the flag 94 mounted on the support carrier pair will be raised, as discussed hereinabove. At station 5, the required mechanism for simultaneously releasing the terminals 13a-13d and 14a-14d of cords that have failed the continuity test may be identical to the previously described terminal release mechanism TRM at station 3.

The elements and associated electrical and pneumatic circuitry utilized to actuate the terminal release mechanism TRM at station 5 in response to a raised carrier flag 94 are shown blocked by phantom dotted lines in FIG. 2, the block being designated as station 5. Referring now to that figure, like numbers and letters in station 5 refer to essentially identical components having like numbers and letters at station 3. Thus at station 5, a photodetector set 230-5 is essentially identical to the photodetector set 230 of station 3 and comprises a light source 231-5 and a photosensitive light receiving photocell 232-5 positioned above the path of carrier advancement to sense the position of a flag 94.

The photosensitive cell 232-5 is connected to an amplifier AMP1-5 and the amplifier AMP1-5 is connected to a timing or time delay relay TR1-5 having internal contacts, not shown. The relay TR1-5 is connected by leads L9 to a solenoid valve SV3-5 that is essentially identical to the solenoid valve SV3 at station 3, by leads L10 to the source S, and by leads L11 to the amplifier AMP1-5. The solenoid valve SV2-5 receives pressurized air from a tube 500 connected to air supply 192 and is provided with an exhaust tube EX5 for exhausting pressurized air from the solenoid valve SV2-5 to atmosphere. The solenoid valve SV2-5 may be energized and driven to selectively direct pressurized air into the tube 246-5 or into the tube 247-5 and thus into respective opposite ends of the air cylinder 242-5. The air cylinder 242-5 encases a reciprocatively drivable piston rod 243-5 which is connected at one end thereof to a terminal release plate 260, FIG. 11, embodied in an essentially identical terminal release mechanism TRM located at station 5. Upon outward movement of the rod 243-5, the rollers 92 of the carrier pair 24a, 24b advancing thereover and carrying the defective cord will be driven upwardly to pivot the jaws 68a-68d of each carrier pair 24a, 24b and thereby release the terminals 13a-13d, 14a-14d carried by the carrier pair 24a, 24b in the same manner as terminal release is effected at station 3.

As discussed hereinabove in regard to the operation of station 3, at station 5, FIG. 2, the interruption of light

beam of the photodetector set 230-5 generates an electrical pulse which is amplified by the amplifier AMP1-5 to initiate the closing of internal contacts, not shown, of the timing relay TR1-5. The initial closing of contacts of the timing relay TR1-5 effects initial energization and movement of the solenoid valve SV2-5 so that pressurized air from the air supply 192 will be directed through the tube 247-5. The piston rod 243-5 is thereby driven upwardly to effect the release of the terminals 13a-13d and 14a-14d from the carrier pair 24a, 24b carrying those terminals. The time delay relay TR1-5 holds the internal contacts open for a time interval sufficient to effect the release cord 10 from the carrier pair 24a, 24b; and thereafter, the relay TR1-5 deenergizes and the contacts of the relay TR1-5 close to effect the deenergization of the solenoid valve SV2-5. The solenoid valve SV2-5 is then driven, for instance by internal springs, not shown, to return to its initial position. Pressurized air from the air supply 192 will be directed by the return movement of the solenoid valve SV2-5 through the tube 246-5 to drive the piston rod 243-5 to the left, as viewed in FIG. 2, so that the plate 260, FIG. 11, of the terminal release mechanism TRM is returned to the position under the path of advancement of the rollers 92 mounted on the next succeeding carrier pair 24a, 24b. Back pressure against the piston rod 243-5 is relieved by exhaust from the tube 247-5, through the solenoid valve SV3-5, and through the exhaust tube EX5 to atmosphere.

As will be evident, if the flag 94 has not been raised at station 4, the light beam of the photodetector set 230-5 at station 5 will not be interrupted by the flag 94 and the terminals 13a-13d and 14a-14d will not be released from the carrier pair 24a, 24b carrying those terminals past station 5. As a result, the cords 10 that satisfactorily pass the continuity test at station 4 proceed to station 6 hanging suspended by the terminals 13a-13d and 14a-14d from a carrier pair 24a, 24b with the loop of the cord in a retracted state.

Cord ejection station 6

At station 6, located at the extreme left-hand end of the machine as viewed in FIG. 1, the carrier pairs 24a, 24b translate beneath an overhead support 600, FIG. 18, which is secured at one end thereof to the top of the housing 25. The other end of the support 600 mounts an arm 602, the arm 602 fixedly mounting a plate 603 by bolts 604. The plate 603 is formed with a downwardly curved edge 605 that is in substantial alignment with the path of movement of the pins 99 projecting from flags 94 carried by carriers 24b.

Also affixed to the outward end of the support 600 is a flat camming plate 606, the vertical plane of the plate 606 being substantially parallel to the vertical planes of the support plates 48 of the carrier pairs 24a, 24b. The camming plate 606 is positioned in substantial alignment with the path of advancement of the rollers 92 carried by both carrier pairs 24a, 24b. The ends of the camming plate 606, FIG. 19, are formed with respective upwardly and downwardly inclined edges 607 and 608; and a flat, horizontal edge 609 is provided therebetween. The carrier pairs 24a, 24b are now supported solely by the link chains 35, FIG. 18, and approach the camming plate 606 with the rollers 92 moving in a plane below the horizontal plane of the edge 609, FIG. 19. The rollers 92 make initial contact with the inclined surface 607 and are pivoted as the carrier pairs 24a, 24b proceed to advance past the plate 606. The camming surface 608 provides gradual pivotal movement to the rollers 92 sufficient to effect the opening of the jaws 68a-68d of both carrier pairs 24a, 24b in respective succession as the rollers 92 ride onto the upwardly inclined edge 609.

As the roller 92 of the carrier 24b rides onto the horizontal edge 607, the carrier 24b passes beneath the flag

lowering plate 603, and the pin 99 contacts the downwardly curved edge 605. Further translation of the carrier 24b beneath the plate 603 causes the pin 99 to pivot counterclockwise, as viewed in FIG. 19, until the pin 99 and the flag 94 is pivoted to the lowered position. The 5 plate 603 thereby insures that the flags 94 on the carriers 24b are lowered before the carrier pairs 24a, 24b return to station 1.

When the rollers 92 of the carriers 24a and 24b are pivoted sufficiently by contact with the edge 608, the terminals 13a-13d and 14a-14d are respectively successively released from the carriers 24a and 24b, and the cords 10 fall by gravity into a chute 610 for receiving acceptable cords, as shown. Empty carrier pairs 24a, 24b with their lowered flags and associated plates 150 proceed to station 15 1 where the carrier pairs are reloaded by the cord loading operator.

As will be apparent to those working in the art, if it is not requisite that the defective spring cords be sorted on the dual basis of observable defects and defects in 20 cord continuity, the cord ejection mechanism and circuitry at station 3 may be omitted from the system 20. The cord inspector at station 3 in raising the flag 94 associated with a carrier pair 24a, 24b would cause the cord carried by that carrier pair to be ejected at station 5 so that cords 25 having both observable and continuity defects would be received by the reject bin at station 5.

Other arrangements of this invention may be devised by those skilled in the art which will embody the principles of the invention and fall within the spirit and scope thereof.

What is claimed is:

1. A system for sorting defective spring cords from nondefective spring cords as the cords advance past successive system stations, each cord being formed with coils and having two ends which include connected pairs of cord terminals, the system comprising:

a conveyor moveable past the stations in one path, clamping mechanism mounted on said conveyor for selectively clamping and releasing connected terminals of a cord, said clamping mechanism being composed of an electrically conductive material so that an electrical connection is provided between said clamping mechanism and the terminals held thereby, signal means mounted on said clamping mechanism and actuatable to provide a signal indicating the presence of a defect in a cord carried by said clamping mechanism,

means at a first station moveable to intercept and extend the coils of a cord while the cord advances, the 50 extension of the cord tensioning the terminals held by said clamping mechanism and facilitating a visual examination of the cord for defects,

means for holding the cord extended during further advancement of the cord from the first station for a 55 predetermined distance in the direction of cord advancement,

means for driving said conveyor and said means for holding the cord extended at substantially the same velocity and in the same direction,

means at a second station located adjacent said one path for monitoring said signal means and producing a first signal in response to the actuation of said signal means, said signal means having been actuated when a defective cord is observed,

means at the second station located adjacent said second path and responsive to said first signal for releasing the said means for holding the cord extended so that the cord hangs freely suspended by the terminals thereof,

means at the second station operated by the last-mentioned means for producing a second signal when the cord loop is released,

clamping release mechanism located at the second station responsive to the second signal and located ad-

jacent said one path for actuating said clamping mechanism so that a cord having an observed defect is released,

means at a third station adjacent said one path for testing the electrical continuity between connected terminals held tensioned by said clamping mechanism and producing a third signal when a lack of electrical continuity between connected cord terminals is detected,

means connected to the last-mentioned means for actuating said signal means in response to said third signal,

second clamping release mechanism at a third station located further in the direction of advancement than said predetermined distance so that said means for holding a cord extended releases the loop after the continuity test is performed thereon whereby the cord hangs freely suspended by the terminals thereof, said second clamping release mechanism being responsive to the actuation of said indicator means for actuating said clamping mechanism so that a cord lacking electrical continuity between the connected terminals thereof is released, and

means at a fourth station located adjacent said one path for automatically actuating said clamping release mechanism so that the cord terminals of a non-defective cord are released.

2. A system for sorting defective spring cords from nondefective spring cords as the cords advance past successive system stations, each cord being formed with coils and having two ends that include electrically connected pairs of cord terminals, the system comprising:

a conveyor moveable past the stations in one path, clamping mechanism mounted on said conveyor for selectively clamping and releasing connected terminals of a cord,

signal means mounted on said conveyor proximate said clamping mechanism and actuatable to provide a signal indicating a defect in a cord carried by said clamping mechanism,

means at a first station proximate said one path and moveable to intercept and extend the coils of a cord while the cord advances, the extension of the cord tensioning the terminals held by said clamping mechanism and facilitating the examination of the cord for defects,

means for holding the cord extended during further advancement of the cord from the first station for a predetermined distance,

means for driving said conveyor and said means for holding the cord extended at substantially the same velocity and in the same direction,

means at a second station located adjacent said one path for monitoring said signal means and producing a first signal in response to the actuation of said signal means,

means at the second station located adjacent said second path and responsive to said first signal for releasing said means for holding the cord extended so that the cord hangs freely suspended by the terminals thereof,

means at the second station initiated by the last-mentioned means for producing a second signal when the cord loop is released,

clamping release mechanism at the second station located adjacent said one path and responsive to the second signal for actuating said clamping mechanism to release the cord terminals of defective cords, and

means at a third station located adjacent said one path for automatically actuating said clamping mechanism so that the cord terminals of nondefective cords are released.

3. A system for sorting defective spring cords from nondefective spring cords as the cords advance past suc-

cessive system stations, each cord being formed with coils and having two ends that include electrically connected pairs of cord terminals, the system comprising:

plural pairs of adjacent carriers movable in a horizontal plane in one path with a cord freely suspended 5 by the terminals thereof between each carrier pair, clamping mechanism mounted on each carrier for selectively clamping and releasing the connected terminals of a cord,

indicator means mounted on at least one carrier of 10 each pair actuatable to provide a signal indicating a defect in a cord carried by a carrier pair,

said carriers being composed of electrical insulating material and said clamping mechanism being composed of electrically conductive material so that an electrical connection is provided between the clamping mechanism and the terminals held thereby,

means at one station proximate said one path and movable to intercept and extend the coils of the cord while the cord advances, the extension of the cord 20 tensioning the terminals held by said clamping mechanism and facilitating the examination of the cord for defects,

means for receiving the extended loop from the last-mentioned means for advancement in a second path 25 substantially parallel to said one path,

means for driving said carriers and said means for receiving the extended loop at substantially the same velocity and in the same direction,

means positioned parallel to said second path for retaining the loop extended during cord advancement to a second system station, 30

continuity test means at a second station located adjacent said one path and including mechanism for making and breaking electrical contact with the advancing clamping mechanism, said continuity test means producing an output signal when a lack of 35 electrical continuity between connected terminals is detected,

means at the second station located adjacent said one path and electrically connected to said continuity test means for receiving the output signals therefrom and operable to actuate said indicator means in response thereto,

means at a third station located adjacent said one path 45 for detecting the actuation of said indicator means and producing a second output signal in response thereto,

clamping release mechanism at the third station responsive to said second signal for actuating said clamping mechanism so that the cord terminals of defective cords are thereupon released, and

means at a fourth station located adjacent said one path for automatically actuating said clamping mechanism so that the cord terminals of nondefective cords 50 are released.

4. A system for sorting defective spring cords from nondefective spring cords as the cords advance to successive stations, each cord being formed with coils and having two ends that include electrically connected pairs of cord terminals, the system comprising:

at least one carrier mechanism for supporting a cord 60 for movement to at least one of the stations, electrically conductive clamping members mounted on said carrier mechanism for selectively clamping and releasing the terminals of each cord end, the cord being freely suspended from said clamping members to form a cord loop,

a signal device mounted on said carrier mechanism and actuatable between first and second positions, 65 actuation of said signal device from the first to the second position indicating a cord defect,

actuator mechanism mounted on said carrier mechanism and insulatively connected to said clamping mechanism for releasing the terminals of the cord held by said clamping mechanism for releasing the terminals of the cord 70 75

held by said clamping mechanism upon actuation of said actuator mechanism,

a first conveyor mounting said carrier mechanism for advancement through the stations in a predetermined path,

a cord extension member located at a first station proximate said predetermined path for intercepting and extending the loop of each cord so that the cord terminals are tensioned by said clamping members and the extended cord rendered examinable for defects,

a second conveyor movable in a second path substantially parallel to said predetermined path and at substantially the same velocity as said first conveyor, a hook pivotally mounted on said second conveyor for receiving the extended cord loop from said cord extension member,

a track of finite length extending substantially parallel to said second path for engaging and pivoting said hook so that the cord loop is held extended by said hook while said hook engages said track, said track terminating a predetermined distance from the first station in the direction of hook advancement,

continuity test mechanism located at a second station adjacent said predetermined path for electrically contacting said clamping members so as to make electrical contact with connected pairs of tensioned cord terminals,

continuity test circuitry connected to said continuity test mechanism for detecting the presence or absence of electrical continuity between connected cord terminal pairs and producing an output signal when an absence of electrical continuity is detected,

a signal actuating mechanism at the second station connected to said continuity test circuitry and positioned to actuate said signal device to said second position upon the receipt of an output signal from said test circuitry,

a detection device located at a third station adjacent said predetermined path and responsive to the second position of said signal device for producing a pulse, clamping release mechanism at the third station connected to said detection device and positioned beyond the point of track termination so that the cord loop is released by said hook before advancing past said clamping release mechanism, said clamping release mechanism being energizable by a pulse from said detection device for actuating said actuator mechanism so that said clamping members release both ends of a defective cord, and

means located at a fourth station adjacent said predetermined path for actuating said actuator mechanism so that said clamping members release both ends of a nondefective cord.

5. A system for sorting defective spring cords from nondefective spring cords as the cords advance to successive system stations, each cord being formed with coils and having two ends that include electrically connected pairs of cord terminals, the system comprising:

at least one pair of adjacent electrically insulated carriers,

electrically conductive clamping members mounted on each carrier for selectively clamping and releasing the terminals of each cord end, the cord being freely suspended from a carrier pair to form a cord loop,

a flag pivotally mounted on one carrier of said carrier pair and moveable between first and second positions, movement of said flag from the first to the second position indicating a cord defect,

actuator mechanism mounted on each carrier and insulatively connected to said clamping mechanism for releasing the terminals of the cord held by said clamping mechanism upon actuation of said actuator mechanism,

a first conveyor mounting said carrier pair for advancement through the stations in a predetermined path, a cord extension member located at a first station proximate said predetermined path for extending the coils of each cord so that the cord terminals are tensioned by said clamping members and the extended cord rendered examinable for defects, 5

a second conveyor moveable in a second path substantially parallel to said predetermined path and at substantially the same velocity as said first conveyor, a hook pivotally mounted on said second conveyor for receiving the extended cord loop from said cord extension member, 10

a track of finite length extending substantially parallel to said second path for engaging and pivoting said hook in one direction such that the cord loop is held extended by said hook while said hook engages said track, said track terminating a predetermined distance from the first station in the direction of hook advancement, 15

continuity test mechanism located at a second station adjacent said predetermined path for electrically contacting said clamping members so as to make electrical contact with connected pairs of tensioned cord terminals, 20

continuity test circuitry connected to said continuity test mechanism for detecting the presence or absence of electrical continuity between connected terminal pairs and producing an output signal when an absence of electrical continuity is detected, 25

a flag pivoting mechanism at the second station connected to said continuity test circuitry and operable to pivot said flag to said second position upon the receipt of the output signal from said test circuit, 30

a detection device located at a third station adjacent said predetermined path and responsive to the position of said flag to produce a pulse when said flag is in said second position, 35

mechanism at the third station connected to said detection device and energizable by a pulse therefrom for actuating said actuator mechanism so that said clamping members release both ends of a defective cord, 40

means located at a fourth station adjacent said predetermined path for actuating said actuator mechanism so that said clamping members release both ends of a nondefective cord, 45

6. A system for sorting defective spring cords from nondefective spring cords as the cords advance to successive system stations, each cord being formed with coils and having two ends that include electrically connected pairs of cord terminals, the system comprising: 50

at least one pair of adjacent electrically insulated carriers, 55

electrically conductive clamping members mounted on each carrier for selectively clamping and releasing the terminals of each cord end, the cord being freely suspended from a carrier pair to form a cord loop, 60

a flag pivotally mounted on one carrier of said carrier pair and moveable between first and second positions, movement of said flag from the first to the second position indicating a cord defect, 65

actuator mechanism mounted on each carrier and insulatively connected to said clamping mechanism for releasing the terminals of the cord held by said clamping mechanism upon actuation of said actuator mechanism, 70

a first conveyor mounting said carrier pair for advancement through the stations in a predetermined path, a cord extension member located at a first station proximate said predetermined path for extending the coils of each cord so that the cord terminals are tensioned by said clamping members and the extended cord rendered examinable for defects, 75

a second conveyor moveable in a second path substan-

tially parallel to said predetermined path and at substantially the same velocity as said first conveyor, a hook pivotally mounted on said second conveyor for receiving the extended cord loop from said cord extension member, 5

a track extending parallel to said second path for engaging and pivoting said hook in one direction such that the cord loop is held extended by said hook during advancement thereof, said track including a moveable section located at a third station for disengaging from and releasing said hook for pivotal movement in a direction opposite said one direction until the extended cord loop is released, 10

continuity test mechanism located at a second station adjacent said predetermined path for electrically contacting said clamping members so as to make electrical contact with pairs of tensioned cord terminals, continuity test circuitry connected to said continuity test mechanism for detecting the presence or absence of electrical continuity between connected terminal pairs and producing an output signal when an absence of electrical continuity is detected, 15

a flag pivoting mechanism at the second station connected to said continuity test circuitry and operable to pivot said flag to said second position upon the receipt of the output signal from said test circuit, 20

a detection device located at the third station adjacent said predetermined path and responsive to the second position of said flag for producing a pulse, 25

means responsive to a pulse from said detection device for moving the moveable track section so as to release said hook for pivotal movement whereby the extended cord loop is released, 30

mechanism at the third station energizable in response to the movement of the moveable track section disengaging from said hook for actuating said actuator mechanism so that said clamping members release both ends of a defective cord, and 35

means located at a fourth station adjacent said predetermined path for actuating said actuator mechanism so that said clamping members release both ends of a nondefective cord, 40

7. A method of sorting a plurality of extensible coiled articles of finite length on the basis of visually detectable defects which would cause the article to be classified as a reject, the method comprising: 45

clamping both ends of each article in substantial adjacency to form an article loop, advancing the clamped ends of each looped article in one direction past a location where observable cord defects are to be visually detected, 50

extending each loop during article advancement to said location to form a substantially V-shaped article configuration with the extended coils of the article lying in one plane, 55

displacing the advancing loop of each extended article from said one plane sufficiently to facilitate a visual scanning of each extended article that advances past said location, and 60

releasing the clamped ends of articles that are considered to be rejectable after the visual scanning thereof so that the extended coils of these articles are free to retract and fling these articles to a location for rejects, 65

8. A method of sorting a plurality of extensible coiled articles of finite length on the basis of visually detectable defects which would cause the article to be classified as a reject, the method comprising: 70

clamping both ends of each article in substantial adjacency to form an article loop, advancing the clamped ends of each looped article in one direction past a location where observable cord defects are to be visually detected, 75

extending each loop during article advancement to said location to form a substantially V-shaped article config-

- figuration with the extended coils of the article lying in one plane,
displacing the advancing loop of each extended article from said one plane sufficiently to facilitate a visual scanning of each extended article that advances past said location,
releasing the clamped ends of articles that are considered to be rejectable after the visual scanning thereof so that the extended coils of these articles are free to retract and fling these articles to a location for rejects, and
releasing the clamped ends of further advanced articles without observable defects so that such further advanced articles are flung to another location.
9. A method of sorting helical spring cords having connected pairs of cord terminals on the basis of the existence or nonexistence of electrical continuity between connected pairs of the cord terminals, the method comprising:
clamping the terminals of each cord end in adjacency to form a cord loop,
advancing the looped cord in one direction by the clamped terminals thereof to a continuity test station,
extending the loop of each cord during cord advancement to the continuity test station to tension the clamped cord terminals,
testing each extended cord that is received by the test station for electrical continuity between the connected terminals thereof, and
releasing the terminals of those cords that are found to be lacking electrical continuity.
10. A method of sorting helical spring cords having connected pairs of cord terminals on the basis of the existence or nonexistence of electrical continuity between the connected pairs of cord terminals and on the basis of visually detectable cord defects which would cause the article to be classified as a reject, the method comprising:
clamping the terminals of each cord end in adjacency to form a cord loop,
advancing the looped cord in one direction by the clamped terminals thereof to a cord observing station,
extending the loop during cord advancement to the cord observing station to form a substantially V-shaped cord configuration, whereby the cord terminals are tensioned and external cord defects made more readily detectable,
releasing the clamped terminals of cords found defective after an examination thereof at the cord observing station so that the released cords are received at a location for defective cords,
further advancing nonreleased cords to a continuity test station,
testing each nonreleased advancing cord at the continuity test station for electrical continuity between the tensioned terminals thereof,
releasing the clamped terminals of cords that said testing station determines to be lacking electrical continuity between the cord terminals thereof, whereby such cords are released to another location for defective cords, and
releasing the clamped terminals of further advanced, nondefective cords to yet another location.
11. A method of sorting helical spring cords having connected pairs of cord terminals on the basis of the existence or nonexistence of electrical continuity between the connected pairs of cord terminals and on the basis of visually detectable cord defects which would classify a cord as rejectable, the method comprising:
clamping the terminals of each cord end in adjacency and in a common horizontal plane to form a freely suspended cord loop,
advancing the freely suspended looped cords in one direction by the clamped terminals thereof to a cord

- observing station with the coils of the cord loops hanging in a substantially vertical plane, the cord terminals being advanced at a substantially equal predetermined velocity,
extending each cord loop during cord advancement to form a substantially V-shaped cord configuration with the plane defined by each loop inclined at an angle to said vertical plane such that the cord terminals are tensioned and cord defects made more readily detectable,
advancing the extended loop of each cord in said one direction at substantially said predetermined velocity through the cord observing station for a visual examination thereof,
releasing the extended loop of each cord that is considered to be rejected after a visual examination thereof,
releasing the clamped terminals of cords considered rejectable after the visual examination thereof so that the completely released cords are received at a predetermined location,
further advancing nonreleased cords to a continuity test station,
testing each extended and nonreleased cord for electrical continuity between the tensioned terminals thereof at the continuity test station,
releasing the extended loop of each cord that is tested for electrical continuity,
releasing the clamped terminals of cords that the test station determines to be lacking electrical continuity, whereby such cords are released to another predetermined location, and
releasing the clamped terminals of further advanced nondefective cords to yet another predetermined location.
12. Apparatus for sorting helical spring cords on the basis of the existence or nonexistence of electrical continuity between connected pairs of cord terminals and on the basis of visually detectable cord defects which would classify a cord as rejectable, the apparatus comprising:
means for clamping the terminals of each cord end in adjacency and in a common horizontal plane to form a freely suspended cord loop,
means for advancing each freely suspended looped cord in one direction by the clamped terminals thereof to a cord observing station and to a continuity test station,
means for extending each cord loop during cord advancement to the cord observing station to form a substantially V-shaped cord configuration whereby the cord terminals are tensioned and cord defects made more readily detectable,
means for advancing the extended loop of each cord in said one direction through the cord observing station for a visual examination thereof,
means for releasing the clamped terminals of cords found rejectable after the visual examination thereof so that defective cords are released to a predetermined location,
means located at the continuity test station for testing each extended and nonreleased cord for electrical continuity between the tensioned terminals thereof,
means for releasing the clamped terminals of cords that the test station determines to be lacking electrical continuity between the terminals thereof so that such cords are released to another predetermined location, and
means for releasing the clamped terminals of further advanced, nondefective cords to yet another location.
13. Apparatus for sorting helical spring cords on the basis of the existence or nonexistence of electrical continuity between connected pairs of cord terminals and on the basis of visually detectable cord defects which would classify a cord as rejectable, the apparatus comprising:
means for clamping the terminals of each cord end in adjacency to form a freely suspended cord loop,

means for advancing each freely suspended looped cord in one direction by the clamped terminals thereof to a cord observing station and to a continuity test station, means for extending each cord loop during cord advancement to the cord observing station to form a 5 substantially V-shaped cord configuration so that the cord terminals are tensioned and the cords positioned for ready scanning, means for holding the cord loops extended during further advancement of the cords, means for advancing the extended loop of each cord in 10 said one direction through the cord observing station for a visual examination thereof, means for releasing the extended loops of cords found rejectable after the visual examination thereof, means for releasing the clamped terminals of cords that are found to be rejectable after the visual examination thereof so that such cords are released to a predetermined location. means located at the continuity test station for testing 20 each extended and further advancing cord for electrical continuity between the tensioned terminals thereof, means for releasing the extended loop of each tested cord, means for releasing the clamped terminals of cords that 25 said test station determines to be lacking electrical continuity between the cord terminals thereof, whereby such cords are completely released to another predetermined location for defective cords, and means for releasing the clamped terminals of further advanced nondefective cords so that the nondefective cords are released to yet another predetermined location.

14. A system for sorting defective spring cords from 35 nondefective spring cords as the cords advance to at least one of a sequence of system stations, each cord having two ends which include connected pairs of cord terminals, the system comprising:
a conveyor for supporting each cord for advancement in 40 one direction, means for driving said conveyor in said one direction, a plurality of clamping mechanisms mounted on said conveyor for selectively clamping and releasing the terminals of each cord that is mounted in a clamping mechanism, each clamping mechanism initially suspending a cord by the terminals thereof to form a 45 cord loop,

signal generating means mounted on said conveyor proximate each clamping mechanism, said signal generating means being operative to indicate that a particular clamping mechanism mounts a defective cord, means located at a first station for extending each cord loop so that the terminals of each cord are tensioned between a mounting clamping mechanism and the extending means, means for holding each cord loop extended during the advancement of each cord, means for driving the holding means in said one direction at substantially the same velocity as said conveyor is advanced, means at a second station responsive to the operation of said signal generating means for actuating those clamping mechanisms that mount cords having visually detected defects so that such cords are released by their clamping mechanisms, continuity test means located at a third station for operating said signal generating means to provide a signal indication that a lack of continuity is detected between connected pairs of terminals of nonreleased advancing cords, means located at a fourth station responsive to signal indications by said signal generating means for actuating those of said clamping mechanisms that mount cords lacking continuity so that such cords are released by such clamping mechanisms while nondefective cords continue to advance, and means at a fifth station for automatically actuating all of said clamping mechanisms so that nondefective cords are released at the fifth station.
